UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed February 17, 1923. Serial No. 619,724.

This invention relates to heel building machines and is designed primarily as an improvement and development of the heel building machine disclosed in applicant's

5 Letters Patent of the United States No. 1,507,014, dated September 2, 1924, although many of its features are applicable to machines of widely different characteristics.

10 The machine of the application referred to is automatic in its operation and comprises a heel assembling mechanism which delivers pasted lifts in the form of a loosely assembled heel into one of a plurality of heel-receiving devices that are carried by 15 and constitute a part of a turret that is rotated in steps through a plurality of operating stations at which various operations, such as alining, pressing and nailing the component lifts, are successively performed, 20 the heels then being discharged from the machine.

25 The principal object of the present invention is to improve and simplify the construction, arrangement and operation of machines of the type described in said Patent No. 1,507,014, with respect both to the several individual features thereof and the general combinations of the component mechanisms, and also to utilize additional features 30 for accomplishing new functions.

35 In another aspect, an object of the invention is to provide an automatic machine for building pasted heels and delivering them in such condition as to be immediately available for compression in a heel compressor.

40 In this regard attention is called to the character of the heel stock supplied to machines of the type in question. It is important that the heels delivered be of equal height, in order that they may still be of equal height after delivery from the heel compressor. Accordingly the supply magazines are loaded with lifts of selected stock, that is, of equal thickness and density, thus 45 making certain a uniform product if the heel contains the full complement of lifts required for its height. Even with this safeguard a heel may lose a lift before the nailing operation takes place, or the full complement may not be supplied at the assembling station due to an exhaustion of the supply of lifts in a magazine or to some 50 other cause.

A further object of the invention, therefore, is to insure a uniform product by eliminating all heels that are too low, before they are nailed. The lifts from these heels may be restored to the magazines for use again, thus the elimination of heels that are too low saves an expensive cobbling operation at a 55 later stage in the manufacture of the shoe. The feature of the invention through which this object is attained comprises a heel measuring mechanism, including a device for determining the height of the heel before it is 60 nailed and for subsequently controlling the nail driving operation, combined with an 65 ejecting device responsive to the action of the measuring mechanism.

More specifically, a further object of the 70 invention is to correlate and arrange in a single, automatic machine, a heel assembling mechanism, a heel alining and nailing mechanism, and a heel pressing mechanism, to provide for operating the various mechanisms in step relation as a single unit, and to further provide for transferring the 75 heels in process of building from one operating mechanism to another in time relation to their operating movements.

80 To the accomplishment of these objects and such others as may hereinafter appear, as will readily be apparent to those skilled in the art, the invention comprises the features and combinations of parts, including 85 improved mechanism for alining the lifts of a loosely assembled heel pile, nailing mechanism adjustable to accommodate heels of any wedge characteristic and height and to definitely locate the securing nail in the 90 heel both as to position and angularity, and mechanism for transferring the nailed heel in a horizontal plane to the heel pressing mechanism and tilting it through 90° to cause it to rest on its breast for loading into 95 the heel press, hereinafter to be described and then particularly pointed out in the appended claims.

100 The various features of the invention will best be understood from a description of the preferred embodiment thereof illustrated in the accompanying drawings, in which: Figure 1 is a plan view of a machine constructed in accordance with the present invention and illustrating particularly the co-operative relation of the heel assembling mechanism, the 105

heel alining and nailing mechanism, and the heel pressing mechanism; Fig. 2 is a view, in front elevation, with respect to the position of the operator, of the heel pressing mechanism; Fig. 3 is an enlarged plan view of the heel alining and nailing mechanism, illustrating in dotted lines the various positions of the heels as they are advanced through said mechanism, certain parts being removed for the sake of clearness; Fig. 4 is a view, in front elevation, from the standpoint of the operator, of the alining and nailing mechanism; Fig. 5 is a view, in side elevation looking from right to left in Fig. 1, of the heel alining and nailing mechanism; Fig. 6 is a view, in rear elevation, of said heel alining and nailing mechanism; Fig. 7 is an enlarged detailed view of certain parts of the heel measuring mechanism; Fig. 8 is an enlarged plan view of the lift alining members; Fig. 9 is an enlarged sectional view of one of the lift alining members, the section being taken on the line 9—9 of Fig. 8; Figs. 10 and 11 are plan views, respectively, of the upper and the lower sections of one of the lift alining members, showing particularly the construction thereof and the staggered arrangement of the cushioning springs; Fig. 12 is an enlarged view, in side elevation, of the lift alining members and the carriage upon which they are mounted; Fig. 13 is an enlarged view, partially in right side elevation and partially in section, of the adjustable heel measuring and nailing head of the heel alining mechanism; Fig. 14 is a sectional plan view, on the line 14—14 of Fig. 13, showing the construction and relationship of certain parts of the heel measuring mechanism that are associated with the adjustable measuring and nailing head; Fig. 15 is a sectional plan view, on the line 15—15 of Fig. 13, showing certain structural details of the heel nailing mechanism; Fig. 16 is an enlarged view, in front elevation and partly in section, of the adjustable heel measuring and nailing head; Fig. 17 is an enlarged view, in side elevation and partially in section, on the line 17—17 of Fig. 4, showing certain of the operating cams and co-operating mechanisms of the heel alining and nailing mechanism; Fig. 18 is a sectional view, on the line 18—18 of Fig. 17, showing the relative arrangement and mode of mounting of certain parts of the nail feed operating means; Fig. 19 is a view, in perspective, of the tilttable heel table adjacent the heel pressing mechanism; Figs. 20 and 21 are views, in end elevation, of said tilttable heel table showing, respectively, the relationship of parts when the table occupies its normal heel-receiving position and after it has been tilted through 90 degrees to turn the heel into a vertical plane, to cause it to rest upon its breast preparatory to being loaded into the heel pressing mechanism; Fig. 22

is an enlarged view, partially in side elevation and partially in section, on the line 22—22 of Fig. 4, showing certain of the operating cams and associated parts of the heel alining and nailing mechanism, and illustrating particularly a portion of the mechanism for subjecting the heel to pressure during the nailing operation; Fig. 23 is a view, in side elevation, of a portion of the pressure applying mechanism shown in Fig. 22, the mechanism being illustrated in its pressure applying position; Fig. 24 is a view, partially in side elevation and partially in section, on the line 24—24 of Fig. 4, showing certain other operating cams and associated parts of the heel alining and nailing mechanism and illustrating particularly a portion of the mechanism for registering or detecting the presence of low heels and subsequently controlling their ejection; and Fig. 25 is a fragmentary view, in front elevation, of a portion of the low heel-detecting mechanism shown in Fig. 24.

In the embodiment of the invention illustrated in the drawings, and referring first particularly to Fig. 1 thereof, the heel building machine constituting the present invention comprises, in general, a heel assembling mechanism designated, in general, by the reference character 30, a heel alining and nailing mechanism designated generally by the reference character 32, and a heel pressing mechanism designated generally by the reference character 34. These main component mechanisms of the machine as a whole, are conveniently disposed in adjacent, side-by-side relation in such manner that the loosely assembled heels produced by the assembling mechanism 30 may be automatically and successively delivered to the alining and nailing mechanism 32 and, subsequently, automatically transferred and delivered to the heel pressing mechanism 34. The component mechanisms referred to are so interconnected and correlated in construction and operation as to constitute a single unitary machine which is fully automatic in its operation and which functions to successively perform all of the heel building operations in producing a pasted heel and delivering it in condition to be immediately finally compressed.

The machine, as a whole, is driven from any suitable source of power by means of a belt co-operating with fast and loose pulleys 36 and 38, which are carried by the shaft 40 of the assembling mechanism 30. The belt is shifted from one pulley to the other by means of a belt shifter 42 in a well-known manner, and the fast pulley 38 is mechanically associated by suitable gearing (not shown) with a jack shaft 44 extending the length of the assembling mechanism 30 and extending beyond it to carry a plurality of sprockets 46 and 48 that are connected, by means of drive chains 50 and 52, respectively,

tively, to the main power shafts 54 and 56 of the heel pressing mechanism 34 and heel alining and nailing mechanism 32.

The heel assembling mechanism 30, although generally similar in construction and operation to the assembling mechanism disclosed in said Patent No. 1,507,014 hereinbefore referred to, is more nearly similar to the assembling mechanism set forth and 10 claimed in applicant's Letters Patent of the United States No. 1,502,082, dated July 22, 1924. In the machine of said Patent No. 1,502,082, the lifts are delivered in the form of a loosely assembled heel-pile upon an 15 intermittently operated receiving conveyer which is adapted to present a dry base lift at the station to which the pasted lifts are delivered, and which is constructed and arranged to be depressed progressively as the 20 pasted lifts are progressively superposed upon the dry base lift. As distinguished from this construction, in the machine of said Patent No. 1,507,014, the lifts from which the loosely assembled heels are produced are delivered successively directly into one of a plurality of receiving devices carried by a rotatable turret. In view of the 25 complete disclosure, in the two prior patents referred to, of the structural details and mode of operation of the lift assembling mechanism, and inasmuch as the assembling mechanism, in the main, pertains to the present invention only indirectly except in so far as it performs a necessary function in 30 the operation of the machine as a whole, only a brief general description of this mechanism will be given.

In general, the lift assembling mechanism 30 comprises a plurality of lift magazines 60 for holding stacks of either wedge or even lifts. The automatic assembly of the lifts into a heel is effected by suitable means for 35 concurrently producing a single lift from the bottom of each of the magazines and concurrently advancing the lifts so produced in a forward direction and depositing them in a row upon a continuously traveling belt or conveyer 62. The traveling belt 62 serves to rapidly feed the lifts in serial relation to 40 a set of continuously driven feed wheels (not shown but found in said prior patents) which function to advance the lifts over a paste roll (not shown but also in said prior 45 patents), by means of which the lower surfaces of all of the lifts are coated with a quick drying paste. The feed wheels, to 50 which reference has been made, also function to deliver the pasted lifts in rapid succession and in superposed relation upon a 55 dry base lift, which previously has been produced from a base lift magazine 64 and suitably presented in position to receive the pasted lifts by means of a transverse lift-receiving conveyer 66, similar to that disclosed 60 in said Patent No. 1,502,082. The

conveyer 66 is adapted to be progressively lowered in position as the lifts are successively piled one upon the other. The receiving conveyer 66 of the present invention, although similar in structure and mode of 65 operation to that disclosed in Patent No. 1,502,082, differs somewhat in details of construction, chief among which is the fact that the conveyer itself lies in a central groove 70 (Fig. 8) formed in an elongated plate 70, 75 leaving the side portions 72 thereof slightly elevated so as to be flush with the upper surface of the conveyer 66, whereby they assist in supporting the heels in definite position during their subsequent advancement by the 80 conveyer.

Referring now particularly to Figs. 3 and 8, the conveyer structure 66 is provided, at its receiving station where the lifts are loosely assembled thereon, with an adjustable breast plate or gage 74 against which the breasts of the lifts engage during the delivering operation. This breast plate 74, in the present machine, is adjustably mounted upon a gate 76, comprising a thin strip 85 of sheet material that lies in a shallow recess in the upper surface of one of the side portions 72 of the grooved plate 70, and which is pivoted upon a pin 78. The gate 76 and breast plate 74 are normally held in the 90 position shown in the figures referred to by means of a spring 80. With this construction, provision is made for permitting the breast plate 74 to yield outwardly in the event that the lifts become displaced and 95 jammed during the delivery operation.

After a heel is loosely assembled upon the conveyer and against the breast plate 74, the conveyer is lowered to a definite position in order to insure a clearance between 100 the uppermost lift of the heel and the feed wheel disposed above it. This operation is effected by means and in the manner of the corresponding operation fully set forth in 105 said Patent No. 1,502,082 and, therefore, no further description thereof is necessary 110 herein, it being sufficient to understand that the heel and conveyer are lowered to a predetermined position subsequent to the delivery of the lifts. Having lowered the heel and conveyer, the conveyer is advanced through a single step by means of a suitable 115 conveyer feeding mechanism (not shown but found in said prior Patent No. 1,502,082). As the heel is thus advanced, it is delivered to the alining and nailing mechanism 32, which then takes control of the loosely assembled heel and operates upon it in the manner to be hereinafter set forth.

Having described briefly the construction and operation of the lift assembling mechanism 30, particular reference may be had to Figs. 3, 4, 5 and 6, which best disclose the alining and pressing mechanism 32. This mechanism, in itself, embodies many of the 120 125 130

main features of the present invention, although its utilization in correlation with the assembling mechanism 30 and the heel pressing mechanism 34 constitutes an important feature of the present invention. The heel alining and nailing mechanism 32 is disposed adjacent the delivery end of the assembling mechanism 30 and is adapted to receive the loosely assembled heels transferred by the conveyer 66 and to subsequently effect their alinement, subject them to pressure and nail together the component lifts thereof. This mechanism also embodies mechanism to measure the height of the heels and if a heel is too low, to prevent the nailing operation and subsequently to effect the ejection or discharge of the low heel. The remaining heels of proper height are successively and automatically delivered to the heel pressing mechanism 34 in which they are held under pressure for a period sufficient for the paste to set.

The heel alining and nailing mechanism 32 comprises, in general, a main supporting frame upon which the various component mechanisms are mounted; a heel support or elevator 86 for receiving the heel from the conveyer 66 and raising it into a position to be further advanced through the machine; a vibratory pusher 88 for delivering a series of impact blows to the breast end of the loosely assembled heel and concurrently advancing it through its predetermined path of movement; a plurality of relatively movable elongated lift alining members 90 between which the heel is advanced by the vibratory pusher 88 and by means of which a wiping action, in conjunction with the vibratory action of the pusher, contributes toward the final alinement of the component lifts; a movable heel support or pressure member 94 upon which the heel is received after passing between the alining members 90 and by means of which the heel is subsequently subjected to pressure during the nailing operation; an adjustable back gage 96 against which the rear end of the heel is positioned by the pusher 88 and which serves in conjunction therewith to maintain the lifts in alinement and definitely position them for the nail driving operation after the heel has been raised into position to be nailed; a measuring device, including the movable heel support or pressure member 94 and also a pivotally mounted measuring finger 98 (Fig. 5) through the agency of which the height of the heel is determined; a nailing mechanism comprising a nail driver 100 (Fig. 13), a reciprocating nail block 102 and a nail supply and feeding mechanism, only the race-way 104 (Fig. 5) of which is shown; an adjustable head 106 upon which the measuring and nailing mechanisms are mounted, which is provided with a lower

pressure surface or member 108 that definitely limits the movement of the pivoted finger 98 during the raising movement of the movable pressure member 94 to subject the heel to pressure during the nailing operation and which, moreover, is mounted for vertical, horizontal and angular adjustment so that the machine may be adapted to operate upon heels of different degrees of wedge or taper, of different heights, and of different styles, requiring different predetermined locations and inclinations or angularities of the securing nail; a low-heel registering device including an adjustable wedge member 112 (Figs. 3 and 24) and a plurality of slideable pins 114 set by said wedge member for temporarily retaining the measurements of low heels for the purpose of subsequently controlling the ejection thereof; a feeding device, in the form of a pusher 116, for laterally removing the heels after they are nailed and advancing them along their prescribed path of movements; a conveyer 118 adapted to receive the heels thus advanced and to transfer them in a series of steps to the heel pressing mechanism 34; and an ejector 120 for automatically discharging the low heels from the conveyer in accordance with the setting of the low-heel registering pins 114.

Referring now particularly to Figs. 4, 5 and 6, the supporting frame of the alining and nailing mechanism 32 comprises a pair of side pedestals 126 and 128 which are connected at the front and rear by a plurality of cross supports 130 and 132 and upon which is mounted a main supporting bed or table 134 which is cored out at 136 (Fig. 5) to provide a recess to receive the outer end of the conveyer 66 when it occupies its lowered position as in Fig. 4. A suitable bracket 138 is bolted to the rear end of the bed plate 134 to carry the vibrating pusher 88 and at the front end of the bed plate a bracket 140 is secured upon which is mounted the adjustable back gage 96. Intermediate these two brackets is located a plurality of upwardly projecting bosses 142 and 143 upon which is slidably mounted a carriage 144 that supports the elongated alining members 90. The heel support or elevator 86 is slidably mounted in a boss 146 projecting upwardly from the cored out portion 136 of the bed plate 134 and the movable heel support or pressure member 94 is similarly slidably mounted in the boss 142.

As already stated, the measuring mechanism including the measuring finger 98, and also the nailing mechanism including the nail driver 100 and nail block 102, are mounted upon the adjustable head 106. This head is suspended, with provision for vertical, horizontal and angular adjustment, from an angular frame support 150, one side

of which is rigidly mounted upon a plurality of vertically extending rods 152 and 154 that are fixed to the bed plate 134. The other side of the frame support 150 is carried by an angular bracket 156, one arm of which is bolted to the frame support and the other arm of which is bolted to the adjacent side pedestal 160 of the lift assembling mechanism 30, as shown in outline in 10 dot and dash lines in Figs. 3, 4 and 6.

Power is supplied to the main drive shaft 56 (Figs. 1 and 5) of the alining and nailing mechanism 32 from the jack shaft 44 of the assembling mechanism 30 through the 15 agency of the driving chain 52 and the intermediary of a safety clutch or coupling 164 of any well-known type which has no direct bearing upon the present invention and will not, therefore, be described. The 20 drive shaft 56 carries at the end opposite the coupling 164 a mitre gear 166 which meshes with a co-operating gear 168 that is fixed to a main cam shaft 170. The cam shaft 170 is suitably journaled in the side 25 pedestals 126 and 128 and is provided with a plurality of operating cams 172, 174, 176, 178, 180, 182, 184, 186 and 188, illustrated best in Figs. 4, 6, 17, 22 and 24. These various cams serve in conjunction with other 30 elements, including a plurality of bell cranks mounted upon a crank shaft 190, to effect the proper time co-operation of the various operating devices of the alining and nailing mechanism 32 with respect to each other and also with respect to the operation of the 35 component elements of the assembling mechanism 30 and the heel pressing mechanism 34.

After a loosely assembled heel has been 40 delivered upon the receiving conveyer 66, and the latter has been lowered into the position indicated in Figs. 4 and 6, the next stepping movement of the conveyer will advance the heel, just assembled, to a position 45 upon the heel support or elevator 86 which at this time lies in the horizontal plane of the lowered conveyer, so that the heel may be easily transferred thereto. The loosely 50 assembled heel having been delivered to the heel elevator 86, the elevator then rises to locate the heel in the plane of operation of the vibratory pusher 88 and the alining members 90. The conveyer 66 may then 55 rise to its normal position, in the manner set forth in said prior Patent No. 1,502,082, in readiness to receive the component lifts of another heel.

The elevation of the heel on the elevator 86 is effected through the agency of the cam 60 182 (Fig. 22) which is co-operatively engaged by a roll 194 carried at the end of one of the arms of a lever 196 pivotally mounted at 198 on the frame and having another arm, the end of which is provided with a 65 slot 200 to receive a roll 202 that is fixed to

the lower end of the stem or post of the elevator 86. A spring 204 is attached to the lever 196 and maintains the cam roll 194 in engagement with its cam 182, thereby tending to raise the heel elevator 86 as permitted 70 by the controlling cam 182.

The heel, having been raised to the position indicated in dot and dash lines in Figs. 5 and 12, is operated upon by the vibratory pusher 88 and advanced in a series of steps 75 or impulses between the co-operating alining members 90. In accordance with an important feature of the present invention, the pusher 88 has a combined and concurrent advancing and vibratory motion so that 80 while actuating the heel through its prescribed path of movement, it also delivers a series of impact blows or impulses to the breast end of the heel for the purpose of alining its component lifts. The pusher 88 is adjustably supported upon a head 210 (Figs. 3 and 5) in such manner that it may be positioned at any desired angle to accommodate varying inclinations of the breast 85 surfaces of different heels as they rest on their heel seat ends. For this purpose, the lower end of the pusher 88 is pivoted at 212 between suitable lugs on the head 210 and the upper end of the pusher is connected by 90 means of a link 214 to a block 216 that is 95 slidably mounted in an inclined slot 218 in the head 210. This block may be raised and lowered in the slot 218 by means of an adjusting screw 220, thereby adjusting the angularity of the pusher 88 as desired. 100 During the subsequent operation of the machine, the heel, after being alined, is raised in position while maintaining full engagement with the pusher 88. It is therefore necessary to make provision for permitting 105 the pusher to be raised while still maintaining its adjusted angular relation. This is provided for by a parallel motion linkage comprising a pair of links 224 that are pivotally connected to the head 210 and also to a slide 226 that is carried in suitable 110 ways 228 in the supporting bracket 138. The lowered position of the pusher 88 is determined by a stop 230 which engages the slide 226, while an unrestricted upward 115 movement of the pusher is allowed by the parallel motion linkage upon which it is mounted. The actuation of the pusher 88 is effected by suitable mechanism which 120 operates with the slide 226 and which comprises an actuating lever 234 (Figs. 5 and 20), the upper end of which is slotted to receive a block 236 pinned to lugs projecting downwardly from the slide 226. The 125 actuating lever 234 is pivotally mounted upon a shaft 235 and its lower extension is acted upon by a spring 237 tending normally to swing the lever to withdraw the pusher to its extreme rear position.

Referring more particularly to Fig. 17, 130

the upper end of the actuating lever 234 is connected by means of an adjustable link 238 with an arm 240, constituting a part of an impact member 242, that is pivotally mounted at 244 upon the end of an arm 246 of a T-shaped lever 248, which is rotatably mounted upon the cam shaft 170. This impact member 242 is provided with another arm 250 having an impact surface against which hammer blows are intermittently directed by means of a projecting lug or hammer member 252 forming a part of a pawl 254 that is also pivotally mounted on the pin 244 and which has a head 256 which is held by means of a spring 258 in engagement with the serrated edge of the notched cam 176. The end of the opposite arm 260 of the T-shaped member 248 is connected by means of a link 262 with the free extremity of the long arm of a bell crank 264 that is pivotally mounted upon the crank shaft 190 and which is provided with a short arm carrying a cam roll 266 having a traveling engagement with the periphery 25 of the cam 178.

The operation of the advancing pusher 88 is as follows:— As the cams rotate in the direction indicated by the arrow in Fig. 17, the short arm of the bell crank 264 is swung in a counter-clockwise direction to correspondingly rotate the T-shaped lever 248 and also the pawl 254 carrying the hammer lug 252. It is therefore clear that the link 238, connecting the actuating lever 234 with the impact member 242, is pulled in a direction toward the left in Fig. 17, thereby causing the lever 234 to advance the feed slide 226, and therefore the pusher 88, into engagement with the heel upon the heel elevator 86. As this advancing movement is continued, the heel also is advanced along its path of movement between the alining members 90.

As already explained, the pusher 88 is given a vibratory movement during its advance, and this is accomplished by means of the hammer pawl 254 operating in conjunction with the notched cam 176. The spring 258, normally maintaining the head 256 of the hammer pawl 254 in engagement with the serrated edge of the cam 176, causes said head 256, as it is advanced in a counter-clockwise direction in opposition to the clockwise movement of the notched cam 176, to be suddenly and forcibly drawn into the successive peripheral notches. Each time this action takes place, the hammer lug 252 carried by the pawl 254 delivers an impact blow to the engaging surface of the arm 250 of the impact member 242. The impact member, therefore, is given a series of rapid and limited oscillatory movements which are transmitted through the link 238 to the actuating lever 234 and thence to the slide 226 and pusher 88. Thus, as the pusher is ad-

vanced in engagement with the heel, it is periodically vibrated and caused to deliver a series of blows upon the breast surface of the heel as it is actuated between the alining members 90. This vibratory action of the pusher is especially effective in producing an accurate and positive alinement of the heel. 70

Another important feature of the invention resides in the construction and operation of the elongated alining members 90 and their cooperative action with the vibratory pusher already described. The utilization of the elongated alining members acting upon a heel that is moved relatively between them has been found to be particularly effective in alining the component lifts by reason of the continued wiping engagement of the alining members as the heel is advanced with respect thereto. Moreover, it 80 has been found that by dividing the alining members into a plurality of layers or sections, each of which is individually spring pressed, a more accurate and effective alinement of the lifts is accomplished by reason 90 of the fact that this construction insures that each of the component lifts shall be acted upon individually and properly positioned with relation to the others. 95

Each alining member 90 (Fig. 8), therefore, comprises a plurality of superposed sections or plates 270, which, in order to accommodate the lateral pitch of a heel, preferably range in width from a wide top plate, as shown in Fig. 10, to a relatively narrow 100 bottom plate, as shown in Fig. 11. The relative widths of the plates depend upon the contour or style of the heel to be operated upon, and in order to care for varying styles and forms of heels it is desirable to construct the machine so that the plates may be removed and interchanged with other sets of alining plates. 105

Each of these sectional alining members 90 is mounted for limited transverse movement in a bracket 272 (Fig. 9) which is provided with two sets of laterally extending ears 274, between each of which the plurality of sections or plates 270 are disposed and positioned by means of vertical pins 276 110 that project loosely through openings 278 and 280 in the respective ends of the several plates. The openings referred to are sufficiently large to permit of a limited transverse movement of the individual plates 270, whereby any particular set of plates may be utilized successfully to aline heels of a number of different sizes which are of the same general style or form. Each of the plates 270 is individually spring pressed at 115 its respective ends by means of a plurality of coiled springs 282 that are disposed in staggered relation to permit of individual springs being used with each of the plates, even though the plates be extremely thin. 120 125 130

- In order to suitably position the coiled springs 282, each of the plates 270 is provided at each end with projecting members 284 which are adapted to be inserted within the springs for holding one end thereof. The opposite ends of the springs are seated in a staggered row of openings 286 that are suitably bored into the upright portion of the bracket 272.
- 5 The pair of elongated and sectional alining members 90 may be bodily relatively adjusted towards and from each other. For this purpose, the farther alining member 90, as viewed in Fig. 8 is stationarily mounted, 10 while its cooperating alining member is mounted for sliding movement with respect thereto. The respective supporting brackets 272 of the co-operating alining member 90 are suitably secured, by means of bolts 290, 15 to a plurality of slides 292 and 294 that are positioned at the respective ends of a transversely extending guideway. The guideway is formed, in part, by a plurality of transverse gibbs 296 (Fig. 12) that are associated with a transversely extending supporting member 298 carried upon the slideable carriage 144. The position of the slide 292 and, therefore, of one of the alining members 90 is determined by an adjustable 20 set screw 300 (Fig. 8) which serves as a stop therefor, and said slide is suitably fixed in position to prevent movement thereof. The other slide 294, upon which the opposite alining member 90 is mounted, is adapted 25 for bodily sliding movement in the guideway and its inward movement with respect to its co-operating alining member is limited by engagement of a pin 302, carried by the slide, with the end of a rod 304 constituting an extension of an adjusting screw 306 located adjacent the adjusting screw 300 for the opposite slide. This movable alining member 90 is normally maintained in its extreme inner position, with the pin 302 in engagement with the rod 304, by means of a 30 coiled spring 308 extending beneath the supporting member 298 and attached at one end to a depending end plate 310 and at the other end to a pin 312 projecting downwardly from said slide 294. By suitable adjustments of the adjusting screws 300 and 306 the initial positions of the co-operating alining members 90 may be accurately determined in accordance with the size of the 35 heels to be operated upon. As the heel is advanced by the vibrating pusher 88 between the co-operating elongated alining members 90, one of said members is capable of bodily outward movement, while the 40 spring-pressed sections or plates 270 of the respective members are capable of independent individual yielding movements to insure an effective wiping engagement upon all of the lifts during the transit of the heel, 45 whereby the desired end is accomplished.
- During the passage of the heel between the alining members 90 it is supported by the upper faces of the transverse ways 296 and of the slides 292 and 294. To properly support the heel in its horizontal plane immediately after leaving the elevator 86, a finger 314 (Figs. 8 and 12) rises from the rear of the carriage 144 to a position between the elevator 86 and the adjacent transverse way 296.
- 50 Although the sections or plates 270 of the respective alining members are adapted for individual yielding movements, the movements of one end of one set of plates are restricted by means of a templet 316 (Fig. 9) which is detachably secured by screws 318 to a portion of the bracket 272 in such position as to be positively engaged by said plates if pressed outwardly a sufficient distance. The width and form of this templet 55 316 is chosen with respect to the style and configuration of the heels to be alined and, as will be understood, definitely determines the form or curvature of the lateral slope of the heel by serving as a positive abutment 60 against which the individual plates of the alining member are caused to engage. As illustrated in Fig. 8 this templet is utilized in connection with the stationary alining member. The movable alining member, by 65 reason of its actuating spring 308, therefore functions to crowd the component lifts of a heel against the stationary alining member until the further ends of its component plates are forced outwardly against the templet, thus definitely insuring the proper alinement and conformation of the heel. By 70 suitably choosing the width and form of the templet 316, a single set of alining plates or sections 270 may be utilized for a considerable range of sizes of heels of any definite shape or style, and moreover, may be also adapted for use in connection with a limited 75 range of heels differing slightly in style or form.
- 80 After the wiping alinement of the heel through the co-operative action of the alining members 90 and the vibrating pusher 88, the heel is delivered upon the movable heel support or pressure member 94 which 85 is disposed immediately at the end of the co-operating alining members and which is suitably positioned to receive the alined heel as it emerges therefrom. During the final 90 advancement of the heel, its curved and sloped rear end is brought into full engagement with the adjustable back gage 96, the inclination of which has been previously adjusted to correspond to the ultimate slope or pitch of the heel. This back gage 96 (Figs. 96 and 5) is pivoted at its lower end to a head 324 and the upper end thereof is connected by a link 326, having an adjustable pin-and-slot connection 328, with the head 324. The head 324, like the corresponding 100

head 210 of the pusher 88, is mounted upon a parallel motion linkage to permit it to be raised and lowered without altering its inclination or angularity. For this purpose, 5 the head is carried by a plurality of links 330, the ends of which are pivoted to the head and also to an upright member of a slide 332 which is suitably positioned in ways 334 associated with the supporting bracket 140. The slide 332 and, therefore, 10 the back gage 96 may be adjusted in accordance with the size and style of heel to be operated upon, by means of an adjusting screw 336 carried by the bracket 140 and 15 operating against a lug 338 depending from said slide. The back gage 96 is normally held upwardly to its limit of movement in engagement with the pressure surface 108 of the adjustable head 106 by means of a spring 240, the respective ends of which are secured to the lower link 330 and to the upright member of the slide 332.

For any given size or style of heel to be operated upon, it is preferable that the back 25 gage 96 be longitudinally adjusted in position so as to be engaged by the heel while the opposite breast corners thereof are still retained in engagement with the rear extremities of the co-operating alining members 90, as illustrated in Figs. 5 and 8. Thus, the alinement of the heel is maintained and the heel held under control during the subsequent operations thereon which involve the raising of the heel support 94 in 30 two steps or stages, first to measure the height of the heel, and second to subject it to pressure during the nailing operation.

In order to permit the heel support 94 and the heel disposed thereon to be raised 40 into position, the stem 346 thereof (Figs. 12 and 22) is slidably mounted through a rectangular extension block 348 that rests upon the boss 142 of the bed plate 134 through which the stem also projects. The lower end 45 of the stem 346 carries a roll 350 which is embraced within the bifurcated end of a lever 352 pivotally mounted upon a shaft 354 carried by the bed plate 134. The other end of the lever 352 carries a cam roll 356 (Fig. 22) co-operating with the cam 180 on the main cam shaft 170. A coiled spring 358 is connected between a portion of the frame and the lever 352 for the purpose of maintaining the cam roll 356 in engagement 50 with its co-operating cam 180.

As the cam 180 is rotated in the direction of the arrow, Fig. 22, and from the position indicated, the spring 358 functions almost immediately to rotate the lever 352 to keep the cam roll 356 in engagement with the drop 360 in the periphery of the cam. This action results in raising the heel support 94 and heel disposed thereon through a definite distance determined and limited by the extent of the drop 360 in the cam. The sup-

port 94 and heel, therefore, are raised through a step which constitutes an initial stage in the operation of measuring the height of the heel and then subjecting it to pressure. 70

Assuming temporarily that the measuring of the heel has taken place, the cam roll 356 is next brought into clearance with respect to its cam by a second drop 362 thereof. At this time suitable means, to be hereinafter described, is brought into operation to raise the heel support 94 and heel through its second step or stage. This movement predetermined in amount whereby to subject the measured heel to a definite degree of pressure against the measuring plate 98 now in contact with the pressure surface 108. 80

Remembering that as the heel is thus raised in steps to measure its height and then to subject it to pressure, and that the rear extremities of the alining members 90 still engage and hold the breast corners of the heel, provision must be made for so supporting the frame 298 upon which the alining members 90 are mounted, that it and the alining members may be raised vertically with the support 94 and the heel thereon. Accordingly the supporting frame 298 is provided with a pair of downwardly projecting pins 368 (Fig. 12) that are adapted to slide vertically through a pair of apertured bosses 370 constituting integral parts of the carriage 144. The actual elevation of the alining members 90 and supporting frame 298 is effected by reason of the slight 90 overlapping of the rear extremities of the alining members with respect to the heel support 94. Therefore, as the heel support 94 is raised into measuring position and then to pressure-applying position, the alining members 90 and supporting frame 298 are correspondingly raised, as permitted by the vertical sliding movement of the pins 368. 100

During these raising movements, the pusher 88 is also maintained in engagement 110 with the breast end of the heel so that the heel is gripped yieldingly between the pusher and the back gage 96. As already stated, the back gage is maintained in its uppermost position by the spring 340. 115 Therefore, as the heel support 94 and heel are raised in steps to measure and to subject the heel to pressure, the heel must necessarily be carried backwardly in the direction of the pusher 88 by reason of the inclination of the back gage. This action 120

would tend to effect a longitudinal and frictional sliding movement between the heel and the engaging rear extremities of the alining members if no provision were made 125 for the alining members to slide backwardly as the heel is correspondingly moved. Furthermore, after having raised the heel to pressure-applying position, it is desirable to retract the alining members 90 from their 130

engagement therewith so as to leave the heel freely supported upon the supporting plate 94 in readiness to be removed therefrom.

- 5 To the accomplishment of these ends, the carriage 144, upon which the supporting frame 298 and alining members 90 are mounted, is constructed and arranged for a limited degree of back and forth movement 10 in a horizontal plane. Accordingly, the rear end of the carriage is provided with an elongated opening 376 (dotted lines Fig. 8) through which loosely projects a stud 378 that is screw threaded into the upper end 15 of the boss 143 of the bed plate 134. Similarly, the forward end of the carriage 144 is provided with an open ended slot 380 (Figs. 8 and 12) to receive the rectangular block extension 348 of the boss 142. 20 The carriage 144 is thus supported upon the bosses 142 and 143 with provision for horizontal sliding movement thereon.
- The actuation of the carriage 144 is effected by means of an operating lever 382 (Fig. 12) the upper bifurcated end of which is pivotally connected to the rear end of the carriage by means of a pin 384. This lever is rotatably mounted upon the shaft 354 and projects downwardly through an opening 386 in the bed plate 134, having its lower end provided with a cam roll 388 (Fig. 22) that has a traveling engagement with the periphery of the cam 184. To maintain proper engagement between the roll 388 and cam 184, a spring 390 is employed, the respective ends of which are connected to the upper portion of the lever 382 and to the boss 143. The carriage 144 and, therefore, the aligning members 90 are thus yieldingly advanced through a limited degree of movement by the spring 390, which also permits the alining members to be partially retracted as the heel moves slightly backwardly during its elevation by the heel support 94. 40 The cam 184 is so designed and timed with respect to the other operating instrumentalities of the machine as to positively retract the alining members 90 from engagement with the heel after the heel has been raised and subjected to pressure preparatory to the nailing operation. Obviously, as soon as this disengagement is effected, the supporting frame 298 with its alining members 90 is permitted to drop by gravity to 45 its initial elevation where, after being advanced by the spring 390, it is in readiness for action upon the next successive heel presented thereto. The yielding advance of the carriage 144 and alining members 90, however, is delayed until the heel support 94 has been lowered to its initial position, in order to permit the slight overlapping of the rear extremities of the alining members with respect to said heel support.
- 50 Having completed the description of the
- construction and operation of the alining members 90, further consideration will now be given to the measuring, pressing and nailing mechanisms, which already have been mentioned in a general way in order to afford a proper basis for the full understanding of the operation of the alining members. Inasmuch as all of the mechanisms, just referred to, are, in whole or in part, carried by the adjustable head 106, it will first be desirable to consider its general structural features and its mode of mounting.
- 55 As best shown in Figs. 3, 4, 5, 6, 13 and 16, the adjustable head 106, considered as a unit, is suspended from the upper frame structure 150 of the machine through the agency of a vertically adjustable carriage 400 (Fig. 6) and a horizontally adjustable carriage 402. The carriage 400 projects outwardly in a horizontal direction from one of the arms of the angular supporting bracket 156 which is provided with a plurality of vertical ways 404 (Fig. 3) in which the carriage 400 is adapted to slide on a plurality of tongues 406 forming a part thereof. The carriage 400 is adjustably supported upon a vertically extending rotatable shaft 408 (Fig. 4) which projects downwardly from the frame support 150 and is screw threaded into a boss 410 projecting upwardly from the horizontal portion of the carriage. This shaft 408 carries a worm wheel 412 co-operatively engaging a worm 414 upon a horizontal shaft 416 that is journaled in the outer webs of the frame support 150. The forward end of the shaft 416 is provided with a hand wheel 418 by means of which the operator may easily raise and lower the carriage to any desired position.
- 60 The carriage 400 is provided with a bottom recess 420 extending from front to rear of the machine which is adapted to receive the horizontally adjustable carriage 402 that is slidably supported upon ways 422 secured thereto by bolts 424. This horizontal carriage 402, as best shown in Figs. 13 and 16, is provided with a pair of longitudinally extending curved ways 426 that are secured to the respective outer sides thereof by a plurality of bolts 428, and these ways serve to support the adjustable head 106 by means of a pair of oppositely extending flanges or tongues 430 that correspond in curvature to the ways. The curvature of the ways 426 and tongues 430 is preferably so chosen that the center of curvature thereof lies substantially in the plane of the upper surface of the heel during the nailing operation, although this relationship is not essential.
- 65 The head 106 preferably comprises a casting having an upper curved wall 434 (Fig. 16), an integral side wall 436, and a back wall 438. A detachable side wall or plate 440 is secured by means of bolts 442 (Fig.

80

130

13) to the side edge of the back wall 438 and also by means of a bolt 444 to a boss 446 projecting laterally from the side wall 436, as shown best in Fig. 16. The lower end of the removable side plate 440 is provided with a longitudinally extending, substantially horizontal cylindrical boss 448 and with a relatively short boss 450 extending beneath the boss 448 and transversely with respect thereto. This shell frame of the adjustable head is utilized to support, in whole or in part, the measuring mechanism and the nailing mechanism, and embodies a member or block 452 disposed in a substantially vertical plane and secured rigidly to the back wall 438 of the head by means of bolts 454, as best shown in Figs. 13 and 15. The upper portion of this block is provided with a cylindrical recess 456 to receive a slidable plunger 458 that carries the nail driving pin 100 of the nailing mechanism, and the lower portion of the block 452 is recessed in such manner as to be substantially channel shaped in section, as shown in Fig. 14. This channel shaped lower portion comprises a plurality of parallel side walls 460 and 462 and a connecting back wall 464, thus providing a rectangular recess 466 therein which is open at the bottom and also at its front. The lower surface of this channel shaped portion of the block 452 constitutes the pressure member 108 that co-operates with the pivotal measuring finger 98 to limit its upward movement when the heel is subjected to pressure during the nailing operation.

Nails are delivered in position to be driven by the nailing pin 100 by means of the reciprocable nail block 102 which is disposed in the recess 466 and is fastened to the rear end 40 of a rod 470 that slidably projects through the cylindrical boss 448 of the side plate 440. This block is maintained in proper position against the rotation of the rod 470 by means of a plurality of longitudinally extending ribs 472 projecting inwardly from the side wall 462 of said channel shaped portion. The nail block 102 is adapted to be periodically reciprocated between a nail-loading station, as indicated in Fig. 13, in which its nail opening 474 is positioned to receive a nail from the tube 476, to a nail-delivery or nail-driving station in which the nail in the opening 474 is located directly beneath the driving pin 100 which is adapted to drive or force the nail so positioned into the heel. The delivery position of the nail block 102 is definitely determined by an adjustable stop or set screw 478 projecting through the rear wall 464.

60 The periodic reciprocations of the nail block 102 are effected through the agency of an operating lever 480, (Figs. 13 and 16) the upper end of which is bifurcated to form two arms 482 that are pivotally mounted upon the shaft 484. This lever 480 carries

at its lower end a laterally extending lug 486 that projects between a pair of washers 488 and 490 carried on the slidable rod 470. The washer 490 abuts against a shoulder 492 on said rod and the washer 488 is held in engagement with the projecting lug 486 by means of a coiled spring 494 that surrounds the rod 470 and abuts against a fixed collar 496 on the end thereof. The operating lever 480 and, therefore, the nail block 102 are normally urged in a direction towards the right, as viewed in Fig. 13, by means of an actuating spring 498 that is attached to the lower end of the lever 480 and to a portion of the head 106. This spring also functions to maintain a cam roll 500 pivotally mounted on the lever 480 in traveling engagement with a cam 502 which is fixed to a continuously rotatable cam shaft 504 that is suitably journaled between the two side walls 436 and 440 of the head 106.

The manner in which the cam shaft 504 is continuously driven is not of present importance and the description of its driving mechanism will therefore be deferred, pending a completion of the explanation of the nailing and measuring mechanisms. Assuming, therefore, that the cam 502 is operated in the direction of the arrow in Fig. 13, the spring 498 is permitted to yieldingly actuate the lever 480 and the nail block 102 to their right hand positions, as determined by the stop 478. Subsequently, the cam 502 causes the roll 500 to actuate the lever 480 and the nail block 102 in the opposite direction. This movement will be yieldingly effected through the intermediary of the coiled spring 494 surrounding the end of the rod 470. It is evident, therefore, that provision is made for preventing any injury to the apparatus which might occur through a jamming of the nail block in its movements in either direction.

The nail driving operation takes place in definite time relation to the movements of the nail block 102, and is effected by the nail driver 100 which is suitably connected to the plunger 458. The lower end of said plunger is provided with oppositely disposed recesses 508 to permit of the reception of the curved bifurcated ends 510 of an actuating lever 512 which carries a roll 514 co-operatively engaging a cam path 516 on the side of the cam 502. This actuating lever 512 is pivoted, by a pin 520, to a triangular shaped bell crank member 522 that is rotatably mounted upon the shaft 484 and is provided with a socket member 526 (Fig. 16) through which a shiftable pin 528 is biased to locking position by a coiled spring 530 surrounding the pin and disposed within the socket. The outer end of the pin is provided with a suitable handle 532 by means of which the pin may be released by the operator against the action of the spring 530. Under

normal operating conditions, the pin 528 is seated within a hole 536 (Fig. 13) in a projecting lug 538 of the side wall 436 of the head 106. Accordingly, the triangular bell crank 522 is locked in such position that the bifurcated ends 510 of the actuating lever 512 are maintained in operative driving engagement with the nailing plunger 458. Thus the nail plunger and nail driver 100 are reciprocated as determined by the cam path 516 of the cam 502.

If it becomes desirable to remove the nail driver 100, for example for purposes of repair or replacement, the operator, by means 15 of the handle 532, may release the locking pin 528 from the hole 536, and after pulling the bifurcated ends of the actuating lever 512 out of engagement with the driving plunger 458, may insert the pin in a second 20 hole 540 in the lug 538. Thus the actuating lever 512 is temporarily held free of the driving plunger 458, and said plunger and nail driver 100 may be readily withdrawn through the top of the adjustable head 106.

25 When the nail driver 100 and plunger 458 are replaced, the operator merely releases the locking pin 528 from the hole 540 and after moving the bifurcated ends of the actuating lever again into operative engagement with the plunger 458 reinserts the pin 528 into the hole 536, thereby locking the triangular bell crank 522 to cause the pin 520 to serve as a fixed pivot point for the actuating lever 512.

30 Means is also provided for detachably connecting the nail driver 100 with the nail driving plunger 458 and for adjusting the position of the driver 100 with respect thereto in order to insure that the heads of the nails are driven flush with the upper surface of the heels. These features, however, form no direct part of the present invention and therefore need not be described.

45 As already set forth, the cam shaft 504 is continuously operated. Under these circumstances, the nail block 102 and the nail driver 100 are actuated in proper time relation to each other and to the other component elements of the machine, so that a nail is 50 delivered to driving position and is subsequently driven into each heel passing through the machine.

55 It is important in building heels that they be of uniform height and, therefore, if one of the lifts is missing, or if for any other reason the heel fails to be of the required height, it is desirable to prevent the nailing operation. Therefore, an important feature of the present invention is the provision of 60 mechanism for automatically detecting the height of each heel prior to the nailing operation and preventing the driving of a nail in the event that the heel is found to be too low.

The heel measuring mechanism through 65 which this end is attained comprises primarily two co-operating elements, first, the movable heel support 94 and second, the pivotally mounted measuring finger 98. This measuring finger 98 (Figs. 13 and 14) comprises a plate that is secured by screws 550 to the under side of one arm of a lever 552, that is pivotally mounted upon a pin 554 carried in the transverse boss 450 and is located adjacent the side wall 462 of the 70 channel shaped lower portion of the block 452. The finger 98 projects laterally beneath the pressure surface 108, as shown by dotted lines in Fig. 14, and is of such shape as to engage the lower edges of the three 75 walls 460, 462 and 464 when raised against them by pressure from a heel upon the movable support 94. The measuring finger 98 is free to move into full engagement with the pressure surface 108, in which case its 80 movement is positively arrested and it thereafter may serve as a fixed pressure member against which the heel may be subjected to pressure by the continued raising of the 85 movable support 94 just prior to the nailing 90 operation.

The measuring finger 98 is provided with an aperture 556 (Fig. 14) which is located directly beneath the nail driver 100 thus permitting a nail being driven therethrough and into the heel. Communicating with this aperture 556 is a V-shaped groove 558 formed in the upper surface of the finger 98 and extending to a point beneath the nail aperture 474 in the reciprocable nail block 102. The point of the nail, therefore, rests in the groove 558 and is thus guided and centered in position as the nail block moves to the right during its nail delivering operation.

100 The lever 552 which carries the measuring finger 98 is preferably yoked, intermediate its ends (see Fig. 14) to straddle the transverse boss 450 of the plate 440 and to have two pivotal bearings upon the opposite extremities of the pivot pin 554. The free extremity of the lever 552 lies in a position to be engaged by a shoulder 562 (Fig. 13) at the lower end of the cam lever 480, whereby 105 said lever 480 may be locked against movement in a direction to cause the nail block 102 to deliver a nail into driving position. A spring 566 is suitably connected to the left hand end of the measuring lever 552 and also to a pin 568 projecting from the plate 440 and serves to maintain the free extremity of said lever in said locking position and, furthermore, to normally hold the measuring finger or plate 98 in its predetermined 110 lowermost position as illustrated in Fig. 13.

115 The exact position of the measuring finger 98, above the movable heel support or pressure plate 94 which also constitutes a part

of the measuring apparatus, depends upon a preliminary adjustment which is made in accordance with the predetermined height of the particular heel to be built. This preliminary adjustment of the measuring finger 98 is effected by raising bodily the adjustable head 106, with all of its associated mechanism, through the agency of the vertically adjustable carriage 400. This is effected in the manner already described by means of the hand wheel 418 and worm-and-gear connections to the threaded rod 408, as best seen in Fig. 4. In making this preliminary adjustment for the height of the heel to be built, the measuring finger 98 is located at such a distance above the pressure member 94 that a heel of proper height will cause a full engagement of the finger with the lower edges of the channel shaped lower portion of the head constituting the pressure surface 108. In so doing, the locking extremity of the measuring lever 552 is depressed sufficiently to be free of the path of movement of the shoulder 562 of the cam lever 480, so that said cam lever may actuate the nail block 102 and deliver a nail in position to be driven. However, if the heel should for any reason be of less than the predetermined height for which the measuring finger is adjusted, said measuring finger is not raised sufficiently by engagement of the heel therewith to remove the extremity of the measuring lever 552 from its position to be engaged by the shoulder 562. Thus the delivery operation of the nail block 102 is prevented, in the event that the heel is found to be too low, because the nail block remains locked and no nail can be positioned beneath the nail driver 100. Hence, although the nail driver is actuated through its full driving stroke, its operation is ineffective.

The measuring operation just described takes place during the first step or stage of the upward movement of the movable heel support 94, which step is always of a predetermined definite amount determined by the drop 360 (Fig. 22) of the controlling cam 180, and is effected yieldingly by the measuring spring 358. The adjustment of the carriage 400, just described, is just sufficient to enable the cam drop 360 to cause a heel of proper height to engage and raise the measuring finger 98 into full positive contact with the pressure surface 108 of the head 106, thus releasing the nail block. On the other hand a heel that is too low will not be moved far enough by the cam drop 360 to elevate the measuring finger 98 and release the nail block.

Subsequent to the measuring operation, the heel support and pressure plate 94 are raised through the second step or stage to subject the heel to pressure prior to the nail

driving operation. It is clear, therefore, that even if the measuring finger or plate 98 is not raised into full positive engagement with the pressure surface of the head during the measuring operation, as would be the case if the heel were too low, still in the subsequent pressure applying stage, the measuring finger 98 would be actuated into full engagement therewith regardless of the height of the heel. It becomes necessary, therefore, to control the nailing operation by some other means than the position of the measuring finger 98 after the measuring stage is over, so as to prevent improper action of the nailing mechanism by the subsequent raising of the measuring finger during the second or pressure applying stage.

For this purpose a cam controlled stop 570 (Fig. 13) is provided which is adapted to permit the nail delivering operation of the cam lever 480 and nail block 102 during the measuring stage, but which is so positioned subsequent to the measuring stage and during the pressure applying stage as to lie in the path of movement of said cam lever 480, which is thereby prevented from operating the nail block to deliver a nail. The stop 570 is rotatably mounted upon a stud 572 carried by the plate 440 of the adjustable head 106 and is provided with a laterally extending boss 574 (dotted lines Figs. 7 and 13) which normally is engaged by a similar boss 576 formed upon a cam arm 578 that is also pivotally mounted upon the stud 572. A coiled spring 580 has its respective ends seated in suitable sockets in the stop 570 and cam arm 578 and serves to normally maintain the adjacent lugs 574 and 576 in engagement. The upper end of the cam arm 578 carries a roll 582 which is positioned to cooperate with a cam 584 so designed as to operate the stop arm 570 in proper time relation to the pressing operation to drop its end into the path of movement of the cam lever 480 and thereby prevent the delivery of a nail to the nail driving device. This relationship of parts is clearly shown in Fig. 7.

In the event a heel of the proper height is on the support 94, the measuring finger 98 is, as heretofore explained, raised to its full extent during the measuring stage thereby permitting the cam lever 480 and nail block 102 immediately to be actuated to their full extent. Subsequent to such actuation the pressure applying operation takes place and during this period a rotation counterclockwise (Fig. 22) of the cam lever 578 by the cam 584 merely causes a compression of the coiled spring 580, by reason of the fact that the stop 570 at this time overlies a shoulder 586 on the cam lever 480.

In this way, the nailing mechanism is rendered responsive to the position of the meas-

uring finger 98 only during the measuring stage and subsequent movements of said finger during the pressure applying stage are ineffective to control the operation of the nailing mechanism.

Whenever the nail block 102 is automatically prevented from delivering a nail to the nail driver 100, as just described, the nail opening 474 still retains the nail in readiness to be delivered at the proper time during the next cycle of operations. This makes it necessary to prevent the feeding of a second nail through the nail tube 476 upon the one already positioned in the nail block. Nails are normally supplied singly and in proper time relation from a suitable nail hopper (not shown) designed to deliver a series of nails into the raceway 104 (Fig. 5) from which they are separated and dropped into the nail tube 476 in a manner well known in the art. The automatic nail supply mechanism is not illustrated because it forms no direct part of the present invention and may be of any well-known construction. The manner in which the automatic nail feed mechanism is operated and controlled in response to the measuring apparatus thus pertain to the present invention, however, and, therefore, this portion of the nail feeding device will be set forth. The nail separator designated by the general reference character 590, applied to Figs. 4 and 5, is periodically actuated by means of a shaft 592 supported in a bracket 594 that is mounted upon the upper frame structure 150 and said shaft is provided with an arm 596 that is fixed thereto, having at its outer end a universal connection 598 with a depending rod 600 shown best in Figs. 4, 13, 17 and 18. The lower end of this rod is slidably mounted within a floating bearing 602 (Fig. 17) having an elongated slot 604 at its lower end to receive a pin 606 carried at the lower extremity of an arm 608 that is secured by screws 610 (Fig. 13) to one of the arms 482 of the cam lever 480. By reason of this construction, the depending rod 600 is swung to the right, as viewed in Figs. 13 and 17, each time that the measuring mechanism permits the cam lever 480, with its associated nail block 102, to operate to deliver a nail into position to be driven and whenever this nail delivery operation is prevented by the measuring mechanism, in the manner already described, the swinging of the rod 600 is also prevented.

Advantage is taken of this peculiarity of operation to arrest the operation of the nail separator whenever the measuring apparatus detects a low heel and prevents the delivery of a nail to the driving mechanism. To accomplish this end, an actuating rod 612 (Fig. 17) is pivotally connected by a

pin 614 to the long arm of the bell crank 264 and its upper end is slidably mounted in a bearing 616 carried by a link 618 having a pivotal connection to an extended portion 620 of a triangular shaped bracket 622 that is suitably secured to the plate 436 of the adjustable head.

The bearing 616 for guiding the upper end of the actuating rod 612 is so positioned with respect to the adjusting head 106 as to always maintain a predetermined relationship between the rods 600 and 612 irrespective of the adjustment of the head. This relationship is such that when a heel of normal height is detected by the measuring mechanism, and the nail block correspondingly actuated to position the nail to be driven, the arm 608 being secured to the cam lever 480, is also actuated to swing the lower end of the depending rod 600 into exact alignment with the end of the actuating rod 612. However, when a low heel is measured, and the delivery operation of the nail block 102 is prevented, the supporting arm 608 for swinging the lower end of the depending rod 600 remains at rest under which conditions the rod 600 is out of alignment with the actuating rod 612 and hence is not affected by its movement.

The actuating rod 612 being attached to the bell crank 264, which with other mechanism is utilized to advance the vibrating pusher 88, is reciprocated intermittently at each cycle of operations of the machine and these reciprocations are imparted to the upper rod 600 whenever said rod has been swung into alignment with the rod 612. In this manner, the rod 600 is actuated whenever a heel of proper height is measured and, in consequence, the separator 590 is operated to separate a nail from the raceway 104 and drop it into the nail tube 476 from whence it is delivered to the nail block 102. When a low heel is detected, the rod 600 is maintained out of alignment with the rod 612, hence the reciprocation of the rod 612 is merely an idle movement and no nail is separated and delivered through the tube to the nail block 102.

Before describing the mechanism for raising the pressure plate 94 to subject a heel to pressure during the nailing operation, the adjustability of the head 106 and associated measuring and nailing devices will be considered. The adjustability of the head constitutes an important feature of the invention since it enables the machine to be adapted to operate upon heels of different styles, heights, and degrees of wedge or taper, and also permits of any desired definite location and angular position of the securing nail.

The vertical adjustment of the head 106 for the purpose of setting the measuring and

nailing devices in accordance with the pre-determined height of the heel to be built, has already been set forth.

To angularly adjust the head in order to accommodate heels of different wedge or taper, it is only necessary to loosen the bolts 428 (Fig. 13) and then rotate the head 106 to a position properly corresponding to the degree of wedge of the heel to be operated upon. The bolts 428 are then tightened and the head thereby fixedly secured in position. Obviously this angular adjustment of the head effects a corresponding adjustment of all of the measuring and nailing mechanism carried thereby. It is evident, therefore, that such an angular adjustment of the head may be utilized to determine the inclination or angular direction in which the nail is driven into the heel. The proper angularity of the driving nail of course depends upon the characteristics of the heel to be operated upon, among which is its general style and its wedge or taper. The general configuration or style of the heel also determines the proper location as well as the angularity of the driving nail and in order that the desired position of the nail along the center line of the heel may be determined, the adjustable head 106 is capable of bodily horizontal adjustment through the agency of the intermediate horizontally adjustable carriage 402 that is supported upon the ways 422, which in turn are bolted to the vertically adjustable carriage 400. By loosening the bolts 424 the carriage 402 and the head 106 supported below it may be adjusted horizontally along the ways 422, after which the bolts 424 may be tightened to hold the parts rigidly in their adjusted positions.

In suitably adjusting the head 106 to accommodate it to the various determining factors of the heel to be operated upon, the inclination of the back gage 96 must be kept in mind since it determines the amount of backward shifting of the heel that is effected as the heel is raised through the measuring position and into the pressure applying position. This inclination of the back gage which corresponds to the pitch of the heel is one of the factors which determines the degree of horizontal adjustment of the head 106 in order that the nail may be properly located with respect to the breast and the rear surfaces of the heel.

By reason of these various adjustments referred to, it is manifest that the location of the cam shaft 504 carried by the head 106 is variable and is capable of adjustment over a considerable area depending upon the peculiar characteristics of the heel operated upon. This cam shaft 504 is continuously rotated during the operation of the machine, as has already been stated, and in order to drive a cam shaft which is thus adjustable both ver-

tically and horizontally, particular provision must be made to permit of such adjustments. Accordingly, as shown best in Fig. 5, the cam shaft 504 is operated from the main cam shaft 170 by a chain drive of the elbow type. This drive comprises a sprocket 630 which is secured to the shaft 170 and which co-operates with a chain 632 (Figs. 4 and 5), the other end of which is carried by another sprocket 634 that is secured to a shaft 636 carried in a bearing member 638 which is supported and spaced from the main cam shaft 170 by an adjustable arm 640. The shaft 636 is also provided with another sprocket 642 which meshes with a vertically arranged chain 644 that also co-operates with a sprocket 646 secured to the cam shaft 504 of the adjustable head. The proper tension of the chain 644 is maintained by an adjustable support and spacing device comprising a bracket 648, an adjustable rod 650, and a yoke 652, the arms of which straddle both of the sprockets 634 and 642, and also the bearing member 638, as shown most clearly in Fig. 4. With a driving connection thus constructed and arranged, the chains 632 and 644 may be maintained in proper tension and the elbow joint thus provided permits of the effective driving of the cam shaft 504 of the adjusting head irrespective of the position to which it is adjusted.

Returning now to the operation of the actuating mechanism for raising the movable heel support or pressure member 94 and subjecting the heel to pressure against the raised measuring finger or plate 98, now in engagement with the pressure surface 108 of the head 106, it will be recalled that the movable heel support 94 is raised in two stages, first, through a predetermined fixed distance by the measuring spring 358 as permitted by the cam drop 360 in the cam 180, and second, by a movement of indeterminate length in accordance with the height of the particular heel being operated upon. The second stage, which subjects a heel of normal height to pressure prior to and during the nailing operation, is effected through the agency of a curved wedge member 660 (Fig. 22) actuated by an operating toggle comprising links 662 and 664. The wedge member 660 is normally adapted to occupy an idle position to one side of the stem 346 of the movable pressure member 94 (Figs. 12 and 22), but is adapted to be positioned beneath and in engagement with the end of the stem 346 (Fig. 23) prior to the application of pressure, and to be subsequently forced upwardly to raise the pressure member 94 and heel thereon by means of the straightening of its operating toggle. To this end the wedge member and operating toggle are constructed and arranged in

- the following manner. The wedge member 660 comprises an arm, the upper end of which constitutes the curved wedge for engaging beneath the stem 346 and the lower 5 end of which has a pivotal connection with the upper end of the toggle link 662 and also with the outer end of a supporting and positioning link 666 which is pivotally mounted upon the main cam shaft 170. Adjacent the upper end of the wedge member 660 a coiled spring 668 is attached, tending to pull said member to the left while this action is normally resisted by means of a cam controlled linkage comprising a link 670 10 that has a pivotal connection at one end upon a pin 672 on the upper end of the wedge member 660 and at its other end with the free end of a cam lever 674, curved to U-shape about the cam shaft 170, which is rotatably mounted upon the bell crank shaft 190. The curved cam lever 674 carries a roll 676 having a co-operative engagement with the cam 186, which engagement is maintained by the spring 668. The design 15 and angular position of the cam 186 is such that after the cam 180 has permitted the measuring spring 358 to raise the movable pressure member 94 through a predetermined distance and sufficient to raise the lower end of the stem 346 above the upper 20 end of the wedge member 60, the cam 186 permits the spring 668 to throw the wedge member 660 to the left, in Figs. 12 and 22, into position beneath the stem 346 as indicated in Fig. 23. By this time the roll 356 25 has reached the second drop 362 in the cam 180. This movement of the wedge is merely preparatory to the application of pressure. By reason of the cam curvature of the wedge member 660 the spring 668 actuates said member until it is brought into firm engagement with the lower end of the stem 346. 30
- Having thus positioned the wedge member 660 in such position that pressure may be applied through it to the stem 346, an actuation of the operating toggle is then effected. When the toggle is straightened, downward movement of the roll 356 on the lever 352 35 is permitted by the low portion of the cam 180 beyond the second drop 362. The links 662 and 664 of the operating toggle are pivotally connected by a pin 678 (Fig. 22) which also serves as a pivotal connection for one end of a toggle operating link 680, the opposite end of which is pivotally pinned to the upper end of one arm of a bell crank 682 rotatably mounted upon the bell crank shaft 190 and having another arm carrying a cam roll 684 that travels in a cam path 686 in one side of the cam 188. The lower end of the lower link 664 of the operating toggle is pivotally connected to an arm of a bell crank 688 also rotatably mounted 40 on the bell crank shaft 190 and having its other arm provided at its lower end with an adjustable set screw 690 for engagement with the under side of the fixed cross support 130. The bell crank 688 is normally held in its raised position by means of a spring 692 connecting the upper arm and a pin 694 carried by the frame. The upper position of said bell crank is determined by an adjustment of the set screw 690, thus determining the vertical position of the wedge member 660 in its normal idle position as may be requisite to insure its proper swinging movement beneath and in engagement with the stem 346. 45
- The thrust of the operating toggle is taken by an adjustable stop 696 threaded on the support 130 against which the lower end of the toggle link 664 engages when it is straightened during the pressure applying operation. By suitably adjusting the stop 696 the degree of pressure to which the heel is subjected may be varied as desired. Obviously, for any given adjustment of the stop 696, the pressure movement of the pressure member 94, through an actuation of the operating toggle by the cam 686, is fixed in amount. Therefore, heels within the allowable range of height are subjected to equal degrees of pressure during the nailing operation. 50
- Subsequent to the nailing operation which takes place while the heels are under pressure, the cam 386 functions to break the operating toggle and the cam 186 to swing the wedge member 660 to one side into its normal idle position. These operations permit the pressure member 94 to be lowered by the cam 180 to its initial position, as shown in Fig. 12. 55
- Having thus lowered the heel, whether it be nailed or not, to its initial position upon the movable heel support 94, said heel is then removed in a lateral direction therefrom by means of the pusher 116 shown best in Figs. 3, 4 and 8. The pusher 116 is adapted to engage one of the sides of the heel and to remove it from the support 94 and transfer it to the intermittently operated conveyor 118 which subsequently carries the heel in a series of steps to the heel pressing mechanism designated by the general reference character 34 (Fig. 1). After the heel has been removed from the heel support 94 by the pusher 116, the alining members 90 are moved forward by the cam 184 to cause their forward extremities to overlap the movable support 94 in the manner already described, in which position they are in readiness to be operated upon by the next succeeding heel. 60
- The pusher 116 is secured to a horizontal rod 700 carried in a bearing 702 that is suitably secured to the frame 160 of the heel assembling mechanism 30. The other end of the rod 700 is provided with a fixed vertical- 65

ly slotted member 704 which co-operatively engages a horizontal pin 706 carried at the upper end of a bell crank 708. This bell crank is rotatably mounted upon a stud 710 threaded into the frame member 160 (Fig. 3) and its lower arm has a pivotal connection with a rod 712 (see also Fig. 24) having its lower end pivotally connected to an arm 714 (Fig. 4) which is secured by a set screw 716 to a short shaft 718 carried in a bracket 720 that is fastened to the side pedestal 126 of the machine. This shaft 718 also carries a bell crank 722, the lower short arm of which is provided with a pin 724 projecting into a recess in a relatively large pin 726 disposed at right angles thereto and mounted in the free end of a cam lever 728. The cam lever 728 is rotatably mounted upon a stud 730 carried by the side pedestal 126 and carries a cam roll 732 held in co-operative engagement with the cam 174 by means of a coiled spring 736. The cam 174 is adapted to effect a periodic reciprocation of the cam lever 728 and through the connections just described impart a corresponding periodic movement of the pusher 116 in proper time relation to advance the nailed or unnailed heel and place it upon the conveyer 118.

The conveyer 118 for automatically transferring the heels from the alining and nailing mechanism 32 to the heel pressing mechanism 34 is similar in construction to the transverse conveyer 66 associated with the assembling mechanism 30 and upon which the heels are loosely assembled. Referring more particularly to Figs. 2, 3, 4 and 8, the conveyer 118 is carried by a plurality of pulleys 740 and 742 that are respectively mounted in bracket 744 and 746, the latter being secured to a frame member 748 of the heel pressing mechanism 34 and to the bed plate 134 of the alining and nailing mechanism 32. The shafts of the respective pulleys 740 and 742 are provided with end members 750 and 752 to which are attached longitudinally extending plates 754, the upper one of which is grooved to receive the conveyer 118 with its upper face flush with the adjacent outer portions of the plate, whereby the heels are firmly supported during their transfer. The pulley 742 is so located with respect to the alining and nailing mechanism that the upper stretch of the conveyer 118 lies in the plane of the movable heel support 94 when said support occupies its lowered position. Thus the heel supported thereon may be readily advanced on to the conveyer by the pusher 116. Like the conveyer 66 of the heel assembling mechanism 30, the conveyer 118 is provided with a plurality of cross pieces 758 against which the heels rest and by which they are advanced. The cross pieces 758 also function as a portion of the conveyer operating mechanism. When on the lower run of the conveyer the pieces

758 are adapted to be successively engaged by a feed pawl 760 (Fig. 4) which is adjustably secured to a bell crank 762 having a pivotal mounting to the upper end of a long arm 764 constituting a part of the bell crank which also comprises the short arm 722 already mentioned. The feed pawl 760 is normally urged in an upward direction into proper operative engagement with the lower stretch of the conveyer 118 by means of a spring 766, the respective ends of which are attached to the short arm of the bell crank 762 and to an adjacent portion of the long arm 764 which constitutes a reciprocating actuating lever for the feed pawl 760. The reciprocating action of the arm 722 through the agency of the cam lever 728 and cam 174, has already been described in connection with the actuation of the pusher 116. By reason of the fact that the operating lever 764 forms an integral part of the bell crank including the short arm 722, it is clear that the feed pawl 760 also is given periodic reciprocating movements. These movements are effective in feeding the conveyer 118 step-by-step to advance the heels delivered thereon into position to be loaded into the heel pressing mechanism 34.

As the heels are thus intermittently transferred from the alining and nailing mechanism 32, they are successively advanced through an ejecting station 770, (Fig. 3) adjacent which is located the ejector 120 and beneath which is disposed a chute 772 to receive and guide the ejected low heels 100 into a suitable receptacle. The ejector 120 operates only on such heels as have been previously determined by the measuring mechanism to be of less than predetermined height, these heels also being un-nailed, as has already been described.

Inasmuch as the heel upon which the measuring mechanism acts is not delivered to the ejecting station by the conveyer 118 until a subsequent cycle of the machine, it is necessary to make provision for registering and retaining the measurement of the measuring mechanism in order that it may subsequently be utilized to control the actuation of the ejector 120. For this purpose, an automatic measurement registering pin setting device comprising the wedge 112 and a plurality of pins 114 is provided, as best shown in Figs. 24 and 25. In order to register the detection of a low heel, at the measuring station the wedge member 112 is disposed at the end of the long arm of the bell crank 776 which is pivotally mounted upon a horizontal rod 778 carried at the upper end of a bracket 780 which is bolted to the side pedestal 126 of the machine. This bell crank is provided with a short arm having an engaging surface 782 disposed immediately above a portion of the movable heel support 94 which constitutes a part of the meas- 130

uring mechanism. The long arm of the bell crank is further provided with a projecting lug 784 which serves as a stop to limit the rotative movement of said bell 5 crank as effected by a spring 786 which is secured to the short arm thereof and also to the bracket 780, as shown in Fig. 24. The stop 784 is so located that the engaging surface 782 of the bell crank 776 is normally positioned at such a height as to be merely engaged by the movable heel support or measuring member 94 when measuring a heel of proper height. If, however, a low heel is delivered to the measuring station, 10 the plate 94 is raised sufficiently to not only engage the surface 782, but also to actuate the bell crank carrying the wedge member 112 at its lower end. The wedge member 112, therefore, is swung to the right as viewed in Fig. 24 only when a low heel is 15 measured and in this position it is so located as to be engaged by the one or the other of a plurality of registering pins 114, held in the opposite ends of an arm 788 that 20 is rotatably mounted upon a shaft 790 carried by the bracket 780. These pins 114 project outwardly through suitable openings in the enlarged opposite ends of the arm 788 and are frictionally held in place by 25 means of coiled springs 792, received in suitable sockets 794 and held in position by adjustable set screws 796. The arm 788 carrying the pins 114 is continuously rotated, 30 in the direction of the arrow in Fig. 24, by means of a sprocket 798, that is secured to the shaft 790 and is driven by a chain 800 running from a sprocket 802 that is fixed to 35 the main cam shaft 170.

Assuming that a low heel is at the measuring station, the wedge member 112 is caused to be swung to the right and position its wedge end in the path of movement of one of the pins 114. As the arm 788 rotates the end of said pin is brought into engagement with the lower surface of said wedge cam and during the continued rotative movement, said pin is carried up the full length of the cam surface and is thus forced through the enlarged end of the lever 788 in which it is mounted and caused to project on the further side thereof. By reason of the frictional engagement of the spring 792 with the pin 114, it is maintained in whatever position it is adjusted. The pin is thus set 50 in position to register the delivery of a low heel to the measuring station and to retain this setting for a period in order that it may subsequently be utilized to control the action of the ejector 120. As stated, if a heel of proper height is measured the wedge member 112 remains at rest so far removed from the arm 788 that the pin 114 is permitted to pass by it without having its position, as shown by Fig. 25, altered.

Having set one of the pins 114 in the man-

ner described, so that the pin projects to the rear in the arm 788, the continued rotation of said arm subsequently brings the projecting pin 114 into engagement with a tail piece 804 (Fig. 24) of the goose-neck 70 ejector 120 that is rotatably mounted upon a pin 806 carried by the bracket 780. The ejector 120 is normally maintained in a retracted position, as shown in Fig. 24, by means of a spring 808 that is secured to the tail piece 804 and to the bracket 780. The relationship of parts at the moment that the said pin 114 is brought into engagement with the tail piece 804 of the ejector is illustrated by Figs. 24 and 25.

As the lever 788 is further rotated, the pin 114 rides down the engaging surface of the tail piece 804 and in so doing swings the ejector 120 in a direction to engage the breast of the heel resting upon the conveyer 118 and occupying the ejecting station. Continued forward movement of the upper end of the ejector forces the heel from the conveyer and causes it to drop into the discharge chute 772. The construction and arrangement of 85 parts of the pin setting registering mechanism and ejecting device is such that the setting of one of the pins 114 in accordance with the detection of a low heel is temporarily retained and the operation of the ejector 90 120 is delayed until such time as the low heel to be ejected is subsequently advanced by the conveyer 118 into the ejecting station.

Continued rotation of the pin carrying arm 788 disengages the pin 114 from the tail 100 piece 804, thereby permitting the spring 808 to return the ejector to its normal idle position. The end of the rearwardly projecting pin is then brought into engagement with an inclined cam surface 810 (Figs. 24 and 105 25) forming a part of the bracket 780 which resets the pin 114 to its initial position by forcing it through the arm 788 in the opposite direction from which it was set by the wedge member 112. The pin 114 therefore is in readiness to perform its intended 110 functions during the next cycle of operations of the machine.

As the nailed heels of predetermined height resting upon their base lifts are advanced in succession by the conveyer 118, they are successively brought to a loading station adjacent the receiving portion of the heel pressing mechanism 34 which broadly considered, may be of any suitable type 115 adapted to receive the heels and hold them under pressure for a sufficient period to allow the paste to set. By employing a heel press of this character, when the heels are finally emerged from the press they are in condition to be placed immediately in a heel compressor and receive their final compression and consolidation. Preferably the heel pressing mechanism is of the tube-type class and may be similar in construction and operation 120 125 130

to the tubular heel press illustrated, described and claimed in Letters Patent of the United States to Fred V. Hart for heel presses, No. 1,475,947, dated December 4, 1923, and assigned to the present assignee. Without describing the details of this heel pressing mechanism, which are set forth in full in the prior patent referred to, a brief, general description of the mechanism will be given to enable a full understanding to be had of the co-operative relation of this mechanism with the other component mechanisms of the present invention hereinbefore described.

The heel press 34, disclosed in skeleton in Figs. 1 and 2, comprises primarily an elongated horizontally disposed heel holder 816, composed of a plurality of side walls 818 that are disposed in opposite pairs to form a substantially rectangular tube through which the heels are forced and by means of which they are held under pressure during the setting of the paste. At intervals throughout the length of the tubular heel holder or press 816, the walls thereof are operated upon by a plurality of spring actuated pressure members, designated by the general reference character 820, which serve to yieldingly press all of the walls in an inward direction and thus produce lateral pressure upon the edges of the heels, when of wedge form. The heels are arranged in the tube in repeated like series of four heels each, in accordance with the method set forth and claimed in Letters Patent of the United States to John B. Hadaway, No. 1,484,642, dated February 26, 1924, and assigned to the present assignee. Heels successively presented to the heel pressing mechanism 34 by the conveyer 118 are received in similar positions by a rotatable loading carrier or positioning device 826 comprising a plurality of heel clamps or gripping devices 828. The clamps 828 receive the heels and manipulate them during the operation of the carrier in such way as to present the heels of each series of four in repeated dis-similar positions at the receiving end of the tubular heel holder or press 816. After each heel is positioned it is loaded in the press by a suitable loading device 830 which serves not only to introduce the heels into the press, but also to force the heels through the press against the frictional engagement of the walls 818, whereby they are discharged, one by one, from the rear end thereof. The period during which they are held under pressure is sufficient to insure a setting of the paste.

With this type of tubular press, in which the press unit extends horizontally, it is necessary to load the heels therein with their component lifts disposed approximately in a vertical plane. Therefore, inasmuch as the heels transferred by the conveyer 118 from the alining and nailing mechanism 32 rest

upon their base lifts it becomes necessary to turn or rotate the heels through 90° in order that they may be presented to the heel press in position to be loaded thereinto.

For this reason, a tiltable table 834, shown generally in Figs. 1 and 2, and in detail in Figs. 19, 20 and 21, is disposed at the heel press end of the grooved plate 754 in which the conveyer travels. The table 834 is so positioned as to normally constitute an extension of the plate 754 so that the heels are advanced by the conveyer upon its receiving surface. The grooved supporting plate 754 is attached to a vertical upright 836 which projects upwardly from the lower supporting plate 754 to which it is also attached. This upright 836, together with the end members 750 and 752, is provided with suitable bearings to carry a rotatable rod 838 upon which the tiltable table 834 is fixed and by which it is adapted for pivotal movement.

Referring to Fig. 19, particularly, the tiltable table 834 comprises a horizontal member 840, a vertical member 842, a plurality of spaced apart, upwardly curved arms 844 terminating in a pair of horizontally disposed lugs or feet 846. The feet 846 are disposed on the opposite side of the conveyer 118 from the member 840 and the upper surfaces of said member and of the feet 846 lie in the horizontal plane of the conveyer 118 and grooved support 754 and are thus adapted to receive the heels as they are successively advanced to the table. As already set forth, the heels upon the conveyer rest upon their base lifts and said heels are tilted upwardly through an angle of 90° as they are successively positioned upon the tiltable table 834, thus changing the position of the lifts from a horizontal to a vertical plane. In order to support the heels after being so tilted, an angular member 848 is adjustably secured by bolts 850 to the normally horizontal member 840 and the normally vertical portion of said angle member 848, after the table is rotated through 90° serves as a horizontal support upon which the heel rests upon its breast end, as shown in Fig. 21.

The tilting movement of the table 834, for the purpose just explained, is effected by means of an arm 852, (Fig. 20) having a pivotal connection to the upper end of a rod 854, also shown in Fig. 24. The lower end of said rod (Fig. 24) is pivotally connected to the outer end of a cam lever 856 that is rotatably mounted upon the bell crank shaft 190. The lever 856 carries a roll 858 co-operating with the cam 172, on the cam shaft 170, in such manner as to periodically produce rocking movements of the tiltable table 834. These movements occur in proper time relation to the operation of the other mechanisms of the machine, so that each heel de-

livered to said tilttable table is rotated from a horizontal to a vertical plane preparatory to being loaded into the heel clamps or gripping devices 828 of the rotatable carrier 826.

5 This loading operation is effected by means of a vertically disposed loading pusher 860 which depends from the forward end of a horizontally slideable rod 862 that is suitably mounted in bearings 863 in the 10 frame of the machine. The loading pusher 860 normally occupies a position in front of the conveyer 118 and is moved rearwardly, when actuated, to pass between the spaced feet 846 of the table to engage the 15 base lift of the heel and introduce it by a horizontal sliding movement into one of the heel clamps 828 which is positioned to receive it.

In order to properly reciprocate the loading pusher 860, an actuating lever 864 (Figs. 1, 3, 6 and 24) has a suitable connection to the rod 862 between a pair of collars 866. This operating lever 864 is rotatably mounted upon an upright shaft 868 that is fastened 25 to the bed plate 134 of the alining and nailing mechanism 132 and said lever also comprises a short arm 870 which has a double pin universal connection 872 (Fig. 24) with the upper end of a cam lever 874, the latter 30 being pivotally mounted upon a stud 876 and carrying a cam roll 878 that co-operatively engages the cam 174. Proper engagement of the roll 878 and cam 174 is maintained by means of a spring 880 which is also adapted 35 to yieldingly actuate the loading pusher 860 to introduce heels into the loading carrier 826 when permitted by the rotation of the cam 174.

Obviously, the loading movements of the 40 pusher 860 are effected periodically, one for each cycle of the machine, and therefore if the conveyer 118 has presented a heel to the tilttable table 834, said heel after being tilted upwardly upon its breast, is introduced into the rotatable carrier of the tubular heel press which properly positions it to be subsequently loaded into the press tube 816 and advanced therethrough while being maintained under pressure. If a low heel has 45 been detected at the measuring station, said heel is subsequently discharged by the ejector 120, hence the conveyer, at times, fails to present a heel to be tilted and introduced into the rotary carrier. At such times the tilttable table 834 and loading pusher 860 operate idly, as will be understood.

Nothing herein contained is to be interpreted as limiting the invention in the scope of its application to use in connection with the particular machine, or the particular mode of operation, or both, selected for purposes of illustration and explanation. While the particulars of construction herein set forth are well suited to one mechanical form

of the invention, it is not limited to these 65 details of construction nor to the conjoint use of all its features, nor is it to be understood that these particulars are essential since they may be variously modified within the skill of the artisan without departing 70 from the true scope of the actual invention, characterizing features of which are set forth in the following claims by the intentional use of generic terms and expressions inclusive of various modifications. 75

What is claimed as new, is:—

1. A heel building machine having, in combination, means for loosely assembling a pasted heel, means for transferring said heel to a nailing station and for alining the lifts thereof while in transit, means for nailing the alined heel, means for holding the heel under pressure while the paste sets, and means for transferring the heel from the nailing station and delivering it to said pressure means. 80

2. A heel building machine having, in combination, means for loosely assembling a pasted heel, a plurality of elongated alining members, means for advancing said heel without change of direction through said alining members and into nailing position, means for nailing the alined heel, and means for holding the nailed heel under pressure 90 while the paste sets. 95

3. A heel building machine having, in combination, mechanism for loosely assembling a pasted heel, mechanism for alining and nailing the heel and mechanism for holding said heel under pressure while the paste sets 100 each located at a separate station, and means operated by the machine for transferring the heel from one mechanism to another.

4. A heel building machine having, in combination, means for loosely assembling a pasted heel, means for holding the heel under pressure during the setting of the paste, means for transferring the heel from one means to the other, and means for alining the lifts of the heel during said transferal. 105

5. A heel building machine having, in combination, automatic means for periodically supplying and immediately assembling a plurality of heel-lifts, automatic means for alining and nailing the assembled heel, a heel 115 press for holding the heel during the setting of the paste, and automatic means for introducing the alined and nailed heel into said heel press.

6. A heel building machine having, in combination, mechanism for loosely assembling a pasted heel, mechanism for holding the heel under pressure during the setting of the paste, mechanism disposed intermediate the assembling and pressing stations for alining the loose component lifts of the heel, and means for transferring the heel from the assembling mechanism through the alining 120 125

mechanism and thence to the heel pressing mechanism.

7. A heel building machine having, in combination, mechanism for successively assembling pasted heels, an alining mechanism operated in time relation therewith, a heel pressing mechanism for holding the heels under pressure during the setting of the paste, means operating in time relation with said assembling mechanism and said alining mechanism for transferring the heels successively from one to the other, and other means operating in time relation with said alining mechanism for transferring the heels therefrom and delivering them to said pressing mechanism.

8. A heel building machine having, in combination, mechanism for successively assembling pasted heels, mechanism for alining the lifts thereof, said mechanisms operating in time relation, normally idle mechanism for holding the heels under pressure during the setting of the paste, means for transferring the heels from one mechanism to the other in turn, and means depending upon the presentation of a heel to said heel pressing mechanism for initiating the operation thereof.

9. A heel building machine having, in combination, means for loosely assembling a pasted heel, means at another station for alining, pressing and nailing said heel, means at a third station for holding the heel under pressure while the paste sets, and means operating in time relation with said first and second means for transferring the complete heel from one operating means to the other in turn.

10. A heel building machine having, in combination, means for pasting and assembling a series of lifts to form a pasted heel pile, a lift alining and heel nailing mechanism and a heel pressing mechanism arranged at separate stations beyond the assembling means in the sequence named, actuating means for both of said mechanisms operating concurrently to aline and nail and to press heels produced by the assembling means, and means for transferring the assembled heels in succession to said mechanisms.

11. A heel building machine having, in combination, means for pasting and assembling a series of lifts to form a pasted heel pile, a lift alining and heel nailing mechanism and a heel pressing mechanism arranged at separate stations beyond the assembling means in the sequence named, and operating means to cause said press to receive a heel, and said alining and nailing mechanism to aline and nail a following heel, at each cycle of the assembling means that produces a complete pasted heel pile.

12. A heel building machine having, in

combination, an assembling mechanism, an alining and nailing mechanism and a pressing mechanism all at separate stations and all operating during the same cycle, and means for simultaneously advancing heels successively from one mechanism to another in the sequence named at successive cycles.

13. A heel building machine having, in combination, an assembling mechanism and alining and nailing mechanism operating upon the heel with its lifts disposed in a horizontal plane, a heel pressing mechanism for subjecting the heel to pressure while the paste sets and operating upon the heel with its lifts disposed in a vertical plane, and means for transferring the heel from the alining and nailing mechanism to said pressing mechanism and for turning the heel lifts from a horizontal plane to a vertical plane prior to an introduction into the press.

14. A heel building machine having, in combination, means for alining and nailing a loosely assembled pasted heel with its lifts in a horizontal plane, a heel-pressing mechanism constructed and arranged to hold a heel with its lifts in a vertical plane and to subject the heel to pressure while the paste sets, and means for transferring a heel from said alining and nailing mechanism to said heel-pressing mechanism and for turning the heel from the horizontal to the vertical plane during the transferral.

15. A heel building machine having, in combination, means for alining and nailing a loosely assembled pasted heel while its lifts are in a horizontal plane, a heel-pressing mechanism constructed and arranged to hold a heel with its lifts in a vertical plane and to subject the heel to pressure while the paste sets, means for transferring the heel from said alining and nailing mechanism to a loading position at said heel-pressing means, and means for turning the transferred heel into a position with its lifts in a vertical plane and loading it into said heel-pressing mechanism.

16. A heel building machine having, in combination, means for alining and nailing a loosely assembled pasted heel while its lifts are in a horizontal plane, a heel-pressing mechanism constructed and arranged to hold a heel with its lifts in a vertical plane and to subject the heel to pressure while the paste sets, means for transferring a heel from said alining and nailing mechanism to said heel-pressing mechanism, a rotatable support in the path of the heel upon which the heel is deposited, means for rotating the support to turn the heel from a horizontal to a vertical plane, and means for loading the heel so turned into the heel-pressing machine.

17. A heel building machine having, in

- combination, means for assembling a series of lifts upon each other in a pile while maintaining the plane of the lifts horizontal, a heel press constructed and arranged to receive heels with their lifts in vertical planes, and means intermediate the assembling means and press for changing the position of the heel pile to position it for loading in the press. 65
- 10 18. A heel building machine having, in combination, means for delivering a series of lifts in a horizontal plane and assembling them one upon another into a heel pile, means for thereafter tipping said pile on edge, a heel press, and means for loading the tipped pile into the press. 70
- 15 19. A heel building machine having, in combination, mechanism for assembling a series of lifts to form a heel pile, a heel press 75 for receiving the heel, and means for transferring the pile to the press and for rotating the pile vertically through ninety degrees before it is received by the press. 80
- 20 20. A heel machine having, in combination, means moving always in one direction for advancing a succession of heels, one at a time, with their lifts disposed in a horizontal plane, a periodically tiltable receiving device for receiving the heels 85 singly and successively turning them through ninety degrees to cause them to rest upon a lateral edge surface, and means operating upon the successive heels so positioned. 90
- 25 21. A heel machine having, in combination, an intermittently operated conveyer for supplying a succession of heels and on which they rest in series with their lifts disposed in a horizontal plane, a pivotally mounted tiltable table straddling said conveyer to 95 which the heels are successively delivered, means for actuating said table to turn the heels through ninety degrees to cause them to rest upon a lateral edge surface, and means for operating upon the successive heels so positioned. 100
- 30 22. A heel machine having, in combination, an intermittently operated horizontally disposed conveyer for supplying a succession of heels and on which they rest with their 105 lifts disposed in a horizontal plane, a pivotally mounted angle member normally disposed with one of its sides in a vertical plane and its other side in the plane of said conveyer, means for tilting said table after a heel has been delivered thereto by said conveyer to turn the heel through ninety degrees and cause it to rest upon a lateral edge surface supported by the side of the angle member previously vertically positioned, and means for removing the heel from said table 110 while maintained in this position. 115
- 35 23. A heel building machine having, in combination, automatic heel assembling mechanism for producing a sufficient number 120 of lifts in a row to form a heel and delivering them in superposed relation at an assembling station, heel lift alining means disposed adjacent to the assembling station, and automatic means for delivering the assembled heel to the control of said alining 125 means. 125
- 40 24. A heel building machine having, in combination, heel assembling mechanism for producing a sufficient number of lifts in a row to form a heel and delivering them in superposed relation at an assembling station, alining means disposed at a point adjacent to the assembling station comprising co-operating members adapted to concurrently engage the respective lateral edges of a heel to effect the alinement of its component lifts, and automatic means for engaging the breast end of the heel and advancing it from the assembling station to and into operative relation with said alining means. 130
- 45 25. A heel building machine having, in combination, heel assembling mechanism for producing sufficient lifts, in dispersed relation, to form a heel and delivering them in superposed relation, an intermittently operated conveyer upon which the lifts are assembled operable to transfer the heel away from the assembling mechanism, a feed member for engaging the loosely assembled heel and removing it from the conveyer, and heel lift alining means independent of the conveyer co-operating with the heel during its advance by the feed member for effecting its lift alinement. 135
- 50 26. A heel building machine having, in combination, automatic assembling mechanism for producing a sufficient number of lifts, in dispersed relation, to form a heel and delivering them in superposed relation, means including a pusher for engaging the lateral surface of the heel and transferring it away from the assembling mechanism, lift alining means co-operating with the respective lateral edges of the heel for effecting the lateral alinement of its component lifts while under control of said pusher, and automatic nailing means for securing together the alined lifts. 140
- 55 27. A heel building machine having, in combination, means for alining and nailing a loosely assembled heel, a heel press, mechanism for delivering heels singly to said press operated in time relation to said means, and a conveyer operated step-by-step, also in time relation, for supporting and transferring a series of heels from said means to said mechanism. 145
- 60 28. A heel building machine having, in combination, means for alining and nailing a loosely assembled heel, a heel pressing mechanism, means including a movable conveyer having spaced cross pieces secured thereto to engage the heel breasts for transferring 150

- heels from one of said means to the other, and means operated in time relation to said alining and nailing means for engaging said cross-pieces and advancing said conveyer in 5 a series of steps. 65
29. A heel building machine having, in combination, means for alining and securing together the component lifts of a loosely assembled heel, means for transferring the heel so alined and secured, and heel pressing mechanism to which the heel is delivered by said transferring means constructed and arranged to be started into operation by the delivery of a heel thereto by said transferring means. 70
30. A heel building machine having, in combination, means for alining and nailing a loosely assembled heel, normally inactive heel pressing mechanism adapted to hold the heel under pressure, for a period of time, means for transferring the alined and nailed heel and presenting it to said heel pressing mechanism, and control means associated with said mechanism and actuated by the presentation of a heel thereto for initiating the operation of said mechanism. 75
31. A heel building machine having, in combination, means for alining and securing together the lifts of a loosely assembled heel, a heel pressing mechanism for holding the heel under pressure for a period of time, means including an intermittently operated conveyer for transferring heels from said first named means to said heel pressing mechanism, and means operating in time relation with said transferring conveyer for loading the heel transferred thereby into said heel pressing mechanism. 80
32. A heel building machine having, in combination, an alining and nailing mechanism for operating upon heels having the component lifts thereof disposed in a horizontal plane, a heel pressing mechanism comprising a horizontally disposed tubular press for receiving heels with their lifts disposed in a vertical plane, and a loading device therefor adapted to receive vertically disposed heels, and means for transferring heels from said alining and nailing mechanism, turning them into said vertical position, and delivering them to said loading device. 85
33. A heel building machine having, in combination, means for alining the component lifts of a loosely assembled heel having its lifts disposed in a horizontal plane, a heel-pressing mechanism comprising a horizontally disposed tubular press for holding and pressing heels stacked therein with their lifts lying in a vertical plane, a normally idle loading device for said press adapted to receive heels having their lifts disposed in a vertical plane and for subsequently loading the heels into said press in stack relation, 90
- means for transferring heels from said alining mechanism, turning the heels into said vertical position and delivering them to said loading device, and control means engaged and actuated by each heel delivered to said loading device for initiating the operation thereof. 95
34. A heel building machine having, in combination, means for alining the component lifts of a loosely assembled heel having its lifts disposed in a horizontal plane, a horizontally extending tubular press for receiving heels in stack formation with their lifts disposed in a vertical plane, and automatic means for transferring the heels from said alining mechanism, turning the heels into said vertical position, and loading them into said press. 100
35. A heel building machine having, in combination, means for supporting a loosely assembled heel, a pair of relatively movable elongated sectional alining members, vibrating means for engaging the breast end of the heel, and means for relatively moving said alining members and said vibrating means to effect an alinement of the component lifts of the heel by a wiping engagement with said alining members. 105
36. A heel building machine having, in combination, means for supporting a loosely assembled heel, a pair of elongated alining members, each comprising a plurality of superposed sections, means for independently and yieldingly acting upon both ends thereof, and means for advancing a heel rear end first between said alining members to effect an alinement of its component lifts. 110
37. A heel building machine having, in combination, means for supporting a loosely assembled heel, a pair of elongated alining members disposed in substantial parallelism and each comprising a plurality of superposed individually spring-pressed sections, means for mounting one of said alining members for bodily movement with respect to the other, and means for advancing a heel between said alining members to effect an alinement of its component lifts. 115
38. A heel building machine having, in combination, means for supporting a loosely assembled heel, a pair of elongated alining members mounted for relative bodily movement with respect to each other and each comprising a plurality of spring-pressed superposed sections adapted individually to adjust themselves to the shape of a heel, 120 means for urging one of said members bodily toward the other, and means for advancing a heel between said alining members to effect an alinement of its component lifts. 125
39. A heel building machine having, in combination, means for supporting a loosely assembled heel; a pair of relatively movable elongated alining members mounted thereon

- each comprising a carrier, a plurality of superposed sections mounted on said carrier severally having elongated transverse openings in the respective ends thereof, pins projecting upwardly from said support and through said openings, and a plurality of coiled springs acting independently upon the individual sections; means tending to urge one of said carriers and its associated alining member towards the other; and means for advancing a heel rear end first between said alining members.
40. A heel building machine having, in combination, means for supporting a loosely assembled heel, a plurality of carriers relatively slidably therein, a plurality of independently spring-pressed superposed sections mounted upon each of said carriers and constituting co-operating alining members, and means for advancing a heel rear end first between said alining members.
41. A heel building machine having, in combination, means for supporting a loosely assembled heel, a plurality of relatively movable elongated alining members, a back gage disposed beyond the end of said alining members and having an inclination corresponding to the desired pitch of the heel, means for advancing a heel between said alining members and into engagement with said back gage, while leaving a portion of the heel in engagement with said alining members, a vertically movable member for supporting the heel in its position in engagement with both the back gage and said alining members and adapted to raise the heel from its alined position, and means associated with said alining members for permitting them to be correspondingly raised while still retaining their engagement with the heel.
42. A heel building machine having, in combination, means for supporting a loosely assembled heel, a plurality of relatively movable elongated alining members, a back gage disposed at one end thereof, means for advancing a heel between said alining members and into engagement with said back gage, means for raising the heel so alined and engaged, said alining members being mounted and arranged for upward movement therewith, and means for withdrawing said alining members from engagement with the heel when the heel occupies its raised position.
43. A heel building machine having, in combination, means for supporting a loosely assembled heel, a plurality of relatively movable alining walls, a vibratory pusher adapted to deliver impact blows to the breast end of the heel and at the same time advance it between said alining walls to effect an alinement of the component lifts, and means for actuating said pusher.
44. A heel building machine having, in combination, means for supporting a loosely assembled heel, a plurality of relatively movable elongated alining members, a pusher having a combined vibratory and advancing movement for engaging the heel and forcing it between said alining members to effect an alinement of the component lifts, and means for actuating said pusher.
45. A heel building machine having, in combination, means for supporting a loosely assembled heel, a pair of spaced alining walls, a back gage disposed at one open end of said alining walls and having an inclination corresponding to the desired pitch of the heel, and means for advancing the heel rear end first between said alining walls and into engagement with said back gage.
46. A heel building machine having, in combination, means for supporting a loosely assembled heel, a plurality of relatively movable alining members, a back gage disposed at the end of said alining members and having an inclination corresponding to the desired pitch of the heel, and a yieldingly actuated vibrating pusher for engaging the breast end of the heel and forcing it between said alining members and into engagement with said back-gage.
47. A heel building machine having, in combination, means for supporting a loosely assembled heel, a plurality of alining members, a pusher for engaging the breast end of the heel, a parallel-motion linkage constructed and arranged to support said pusher while permitting vertical movement thereof, and means for actuating said pusher to advance the heel between said alining members.
48. A heel building machine having, in combination, means for supporting a loosely assembled heel, a plurality of co-operating alining members, a pusher for engaging the breast end of said heel, said pusher being capable of being set and held at varying angles to suit the inclination of the heel breast, and means for actuating said pusher to advance said heel between said alining members.
49. A heel building machine having, in combination, means for supporting a loosely assembled heel, a plurality of co-operating alining members, a pusher for engaging the heel, and means for actuating said pusher to advance the heel between said alining members comprising a cam-actuated mechanism for producing a steadily advancing movement of said pusher, and an intermittent impact-device operating upon said actuating mechanism for effecting vibratory movements of said pusher during its advance.
50. A heel building machine having, in combination, means for assembling and nail-ing together the component lifts of a heel,

an intermittently operated conveyer abutting the nailing station, a pusher operated in time relation with the conveyer for engaging the nailed heel at the nailing station 5 and moving it on to the conveyer, and means operable upon a heel upon said conveyer for effecting its discharge.

51. A heel building machine having, in combination, means for assembling a plurality of lifts to form a heel, a heel support for receiving and supporting said heel, an intermittently operated conveyer disposed in the plane of said support, operating means disposed above said support, means 10 for raising said support and the heel thereon into position to be operated upon by said operating means, and for subsequently lowering the support and heel to the plane of said conveyer, and means for engaging the 15 heel after being operated upon and delivering it to said conveyer.

52. A heel building machine having, in combination, means for loosely assembling a plurality of lifts in the form of a heel, 20 means for alining the component lifts thereof, means for measuring the height of said heel, and means dependent upon the action of said measuring means for nailing together the component lifts of the heel.

53. A heel building machine having, in combination, means for loosely assembling a plurality of lifts in the form of a heel, means for alining the component lifts thereof, nailing mechanism for securing together 35 the component lifts thereof, and means operable to detect heels of less than a predetermined height and prevent the driving of a nail therein.

54. A heel building machine having, in combination, means for loosely assembling a plurality of lifts in the form of a heel, means for alining the component lifts thereof, means for nailing together the lifts when alined, means for preventing the 40 operation of said nailing means when the heel is too low, and means for subsequently subjecting the heel to pressure, irrespective of its height.

55. A heel building machine having, in combination, means for loosely assembling a plurality of lifts in the form of a heel, means for alining the component lifts thereof, means for measuring the height of the heel and then subjecting it to pressure, and 55 means for nailing together the lifts of the pressed heel only when the measuring operation detects a heel of a predetermined height.

56. A heel building machine having, in combination, means for loosely assembling a plurality of lifts in the form of a heel, means for alining the component lifts thereof, heel nailing mechanism, heel measuring and pressing mechanism, and a device for

controlling the supply of nails to the nailing 65 the actuation of which is determined by the height of the heel when measured.

57. A heel building machine having, in combination, means for alining the lifts of a loosely assembled heel, a nailing mechanism for securing the lifts together, means for measuring the height of said heel before being nailed and preventing the nailing thereof if too low, means for removing the heel from the nailing station, and means 70 responsive to said measuring means for ejecting any low heel after it has been removed from the nailing station.

58. A heel building machine having, in combination, means for loosely assembling 80 a plurality of lifts in the form of a heel, means for alining the component lifts thereof, a heel support, a movable controller disposed above said heel support, means for raising the heel support a predetermined distance to cause the heel, if of proper height, to engage and actuate said controller, and nailing means, the effective operation of which is determined by the action of said controller.

59. A heel building machine having, in combination, means for loosely assembling a plurality of lifts in the form of a heel, 90 means for alining the component lifts thereof, a heel support, a nailing mechanism, a movable controller, arranged above the heel support, the movement of which to a predetermined extent permits a nail to be driven but a movement of which to a lesser extent prevents the driving of a nail, and means for raising the support through a distance to fully complete the controller movement only if a heel of proper height is on the support.

60. A heel nailing machine having, in combination, means for assembling a plurality of lifts to form a heel, means for supporting said heel, a measuring device disposed above said heel support, means for raising the heel support a distance which causes it to engage and actuate said measuring device only if the heel thereon is of proper height, a periodically operated nail driver, a movable nail block adapted to receive a nail and deliver it into position to be driven, and means co-operating with said measuring device for preventing the delivery of a nail by said nail block if the heel is too low to actuate said measuring device.

61. A heel nailing machine having, in combination, means for assembling a plurality of lifts to form a heel, a movable support for said heel, nailing mechanism disposed a predetermined distance above said support and comprising a periodically operated nail driver, a movable nail block adapted to receive a nail and deliver it into position beneath said driver, a measuring

- member disposed above said heel support and normally adapted to restrain the delivery movement of said nail block, and means for raising the heel support a predetermined distance to cause the heel thereon, if of proper height, to engage and actuate said measuring member, whereby said nail block is released to deliver a nail to the nail driver.
- 10 62. A heel nailing machine having, in combination, means for assembling a plurality of lifts to form a heel, means for receiving and supporting said heel, means for driving a nail therein, means for delivering a nail in position to be driven, and means for measuring the height of the assembled lifts on said support and preventing the effective operation of said nail driving means if the heel is too low.
- 15 63. A heel nailing machine having, in combination, means for assembling a plurality of lifts to form a heel, means for driving a nail therein, means for periodically delivering a nail beneath the nail driving means, means for feeding single nails periodically to said delivering means, and means for measuring the height of the assembled lifts and preventing the operation of said nail feeding means if the heel is too low.
- 20 64. A heel nailing machine having, in combination, means for assembling a plurality of lifts to form a heel, means for supporting said heel, a periodically operated nail driver disposed above said heel support, a nail block for receiving a nail and movable periodically to deliver it in position beneath the driver, a nail supply, means for feeding nails singly therefrom to said nail block when in its receiving position, and measuring means, normally restraining the delivery movement of said nail block, and actuated to release said nail block only when a heel of proper height is upon the heel support.
- 25 65. A heel nailing mechanism having, in combination, means for assembling and nailing together the component lifts of a heel, means for measuring the height of the assembled lifts, and means operative to feed a nail to said nailing means in the event the heel is found to be of proper height by said measuring means, but to prevent the supply of a nail to said nailing means in the event the measuring means detects a low heel.
- 30 66. A heel nailing mechanism having, in combination, means for assembling and nailing together the component lifts of a heel, means for measuring the height of the assembled lifts, and means for supplying a nail to said nailing means comprising a nail separator, a continuously reciprocated actuating member, and a separator operating member automatically positioned for engagement by said actuating member only when the measuring means registers a heel of proper height.
- 35 67. A heel nailing machine having, in combination, means for assembling a plurality of lifts to form a heel, means for supporting said heel, a measuring device disposed above said heel support, means for raising said support a predetermined distance to cause the assembled lifts, if of proper height, to engage and lift said measuring device, means for subsequently further raising the support to subject the lifts to pressure, during which movement the measuring device may be lifted by a heel of improper height, a normally inoperative heel nailing mechanism for driving a nail into the lifts while under pressure, and means controlled by the movement of said measuring device during the measuring period only, for rendering said nailing mechanism operative.
- 40 68. A heel nailing machine having, in combination, means for assembling a plurality of lifts, a vertically movable support for said heel, a fixed pressure member disposed above the said heel, a movable measuring device disposed beneath said fixed pressure member in the path of movement of the heel, a normally inoperative heel nailing mechanism, means for raising the support in two steps, first to measure the assembled lifts and second to subject the lifts to pressure, and means co-operating with said measuring device for controlling the effective operation of said nailing mechanism in accordance with the movement of said measuring means during the first raising step of the heel support.
- 45 69. A heel machine having, in combination, means for forming a heel from separated lifts and delivering it to a heel support, means for measuring the height of the heel thereon, means for removing the heel therefrom for another operation thereon, and means dependent upon the action of said measuring means for ejecting the heel after its removal from said support.
- 50 70. A heel machine having, in combination, means for forming a heel from separated lifts and delivering it to a heel support, means for measuring the height of the heel thereon, means for removing the heel after being measured for another operation thereon, and means set by said measuring means and operable only when the heel has been removed from said support for effecting the discharge thereof.
- 55 71. A heel nailing machine having, in combination, means for forming a heel from separated lifts and delivering it to a heel support, means for measuring the height of the heel, auxiliary means comprising an adjustable device for registering said meas-

- urement if too low, controlled by said measuring means and adapted temporarily to perpetuate its registration of the low heel measurement, means for advancing the heel 65
 5 after being measured, and a discharge device located at a point removed from the measuring station and rendered operative by said auxiliary means to effect the discharge of said low heel when it reaches said point.
10. 72. A heel machine having, in combination, means for forming a heel from separated lifts and delivering it to a heel support, means for successively measuring the height of heels on said support and tempor- 70
 15 rarily perpetuating said measurement of any heel that is too low, means for advancing the heels after being measured for another operation thereon, and means disposed at a discharge station in the path of movement of said heels and rendered operative 75
 20 by said registered measurement to act upon said low heel and discharge it at said discharge station.
73. A heel machine having, in combination, means for assembling a plurality of lifts to form a heel, means for measuring the heel and effecting its discharge at separated stations, means for moving the heel from one station to the other, and means controlled 80
 25
 30 by the measurement of the heel at the measuring station for subsequently controlling the operation of said discharge means upon said heel when it arrives at the discharge station.
35. 74. A heel machine having, in combination, means for assembling a plurality of lifts to form a heel, means for advancing the heel in a definite path of movement through the machine and through separated measuring and ejecting stations, means operable 85
 40 at the measuring station for determining the height of the heel, means operable at the discharge station for effecting its discharge, and delayed means set in accordance with 90
 45 the measured height of the heel at the measuring station for determining the operation of the discharge means when the measured heel arrives at the discharge station.
75. A heel machine having, in combination, means for assembling a plurality of lifts to form a heel, means for receiving and supporting said heel, means for measuring the height of the assembled lifts, a nail driving mechanism, means controlled by said 95
 50
 55 measuring means for determining the operation of said nail driving mechanism, means for removing the heel from said support, and means dependent upon said measuring means for effecting its discharge.
60. 76. A heel machine having in combination, means for assembling a plurality of lifts to form a heel, means for advancing the assembled lifts through a nailing station and a discharge station, nail driving means 100

a pair of relatively movable alining members disposed in advance thereof, a back gage disposed at the end of said alining members and beyond said movable support, a stationary pressure member above said movable support, means for advancing the heel between said alining members and upon said movable support with its curved end in engagement with said back gage and its breast corners held between the ends of said alining members, means for raising said movable support to subject the alined heel to pressure against said pressure member, and means for permitting said alining members to be raised with the heel and for subsequently withdrawing said alining members from engagement with the heel.

83. A heel building machine having, in combination, a plurality of relatively movable alining members, a back gage disposed beyond said alining members, means for advancing a loosely assembled heel between said alining members and against said back gage with its breast corners remaining in engagement with the rear ends of said alining members, means for raising the alined heel as it is held in engagement with said back-gage and the ends of said alining members, and means for permitting the alining members to be raised with said heel and for subsequently withdrawing said alining members from engagement therewith.

84. A heel machine having, in combination, a stationary upper pressure member, a movable lower pressure member upon which the heel is supported, means for yieldingly raising the support and heel a predetermined distance to effect its measurement, a toggle-operated wedge member adapted to be positioned beneath and in engagement with said movable support after the measuring operation, and means for actuating said toggle to cause said wedge member to raise said movable support and subject the heel to pressure against said stationary support.

85. A heel assembling and nailing machine having, in combination, means for assembling a plurality of lifts to form a heel, a support for said heel, a nailing mechanism disposed above said support and comprising a nail driver and means for delivering nails thereto, a head upon which the nailing mechanism is mounted, and means for adjusting said head in position to accommodate any size of wedge characteristic of the heel or any location of the nails to be driven therein.

86. A heel assembling and nailing machine having, in combination, means for assembling a plurality of lifts to form a heel, a support for said heel, a nailing mechanism disposed above said support and comprising a nail driver and means for delivering nails thereto, a head upon which the nailing mechanism is mounted, and means for adjusting

said head vertically to accommodate any height of heel, angularly to determine the angle at which the nail is to be driven, and longitudinally from the breast to the rear end of the heel to determine the location of the nail to be driven.

87. A heel assembling and nailing machine having, in combination, means for assembling a plurality of lifts to form a heel, a support for said heel, a nailing mechanism disposed above said support and comprising a nail driver and means for delivering nails thereto, a movable head upon which the nailing mechanism is mounted, constructed and arranged to be adjusted vertically, horizontally and angularly to definitely determine the nail driving operation, and means for supplying power to the operating parts of the nail driving mechanism while permitting adjustments thereof.

88. A heel assembling and nailing machine having, in combination, means for assembling a plurality of lifts to form a heel, a support for said heel, nail driving mechanism disposed above said support, means for operating said nail driving mechanism, an adjustable head upon which the nail driving mechanism is mounted, constructed and arranged to permit of vertical, angular and horizontal adjustments in order to definitely determine the nail driving operation, and means for supplying power to said nail driving mechanism irrespective of its adjusted position.

89. A heel assembling and nailing machine, having, in combination, means for assembling a plurality of lifts to form a heel, means for supporting said heel resting upon its base lift, a head disposed above said support and adapted to be adjusted vertically, angularly and horizontally with respect thereto, a nail driving mechanism carried by said head for supplying and driving a nail in proper position into the heel, and means for supplying power to said nail driving mechanism constructed and arranged to permit of any adjustment thereof.

90. A heel assembling and nailing machine having, in combination, means for assembling a plurality of lifts to form a heel, a movable support for said heel, an adjustable head disposed above said support and having a heel engaging surface constituting a fixed pressure member, means for raising the heel support to cause the heel to engage said pressure member, a nail driving mechanism carried by said head and adapted to drive a nail through an opening in said pressure member and into the heel, and means for adjusting the head vertically, angularly and horizontally to enable the machine to operate upon heels of any desired height, degree of wedge or location of nails.

91. A heel assembling mechanism having,

in combination, means for producing a series of lifts sufficient to form a heel, means for feeding said lifts serially and delivering them in superposed relation in the form of a heel-⁵ pile, and a receiving device into which the heel is loosely assembled having a gage against which the lifts are delivered and constructed and arranged to yield in the direction of feed of the lifts under predeter-
¹⁰ mined conditions.

92. A heel building machine having, in

combination, means for loosely assembling a plurality of lifts in the form of a heel and for presenting a succession of such heels to a measuring station, means at said station ¹⁵ operable to detect heels of less than a predetermined height, and nailing mechanism under control of said height detecting means and rendered inoperable thereby when a heel of less than a predetermined height is de-²⁰ tected.

ERASTUS E. WINKLEY.
